UNITED STATES PATENT OFFICE

HERBERT M. FRIENDLY, OF PORTLAND, OREGON; MILTON S. FRIENDLY AND CENTRAL TRUST COMPANY OF ILLINOIS EXECUTORS OF SAID HERBERT M. FRIENDLY, DECEASED

TELEPHONE SYSTEM

Application filed October 21, 1921. Serial No. 509,263.

The present invention relates in general to automatic telephone systems, and is particularly adapted to a system that includes a main exchange having a branch exchange tributary to it.

More specifically, the invention relates to an improved method and apparatus for permitting connections to be passed, transferred, or extended successively from station to station in a connection primarily established from a calling telephone to a first called telephone, the calling telephone being directly tributary to the said main exchange, and the called telephone being tributary to a said branch exchange; the latter known in the art as a private automatic exchange, located on the premises of a subscriber, and involving a plurality of telephones related for automatic interconnection, and for incoming and outgoing service with the main exchange over one or more trunk lines.

Other systems have been invented which contemplate certain functions of this nature. However, the present invention contemplates additional novel functions, together with improvements in the structure, and operation of such a system consistent with realizing the novel functions.

Heretofore, so far as I am aware, call connections which are enabled to be passed within the private automatic exchange must have been originated from without, and extended over a trunk line from the main exchange to terminating equipments in the private automatic exchange, and thence to desired called stations within the private automatic exchange, directed from the calling station, or from a called station, or possibly from either the calling or a called station, as preferred.

A salient object of the present invention is to not only enable calls to be completed to the private automatic exchange, and then passed from station to station, but to allow calls originating within the private automatic exchange to be completed over a trunk line to the main exchange and thence to a station therein, and forthwith thereafter pass the connection at the calling end. For example, an attendant or other party at a station within the private automatic exchange

will directly establish a connection to a desired party in the main exchange and thereafter pass the calling connection at the private automatic exchange end to a successive station, the operative details, so far as the users are concerned, are as if the call had been extended from the main exchange to the calling station in the private automatic exchange in lieu of the call having been extended from the private automatic exchange to the main exchange.

From the foregoing general statements it will appear that the present invention contemplates that outgoing and incoming calls are resolved into the same service relation at the private automatic exchange so that supervision, operation, and service is the same, regardless of whether a call is outgoing or incoming. Moreover, the present disclosure shows means wherein the same trunk terminating equipments at the private automatic exchange is brought into requisition in passing connections, regardless of which end of the trunk is the originating end.

In general, the novel operation of the present invention is as follows: On calls originating in the main exchange the first available trunk to the private automatic exchange is attained by operating an automatic calling device whereby the call is directly extended from the calling telephone through the selectors to a connector having access to the private automatic exchange trunks, in a way generally well known, the connector, however, being novel and has novel operative functions as will appear presently. Upon the first disengaged trunk being seized the trunk terminating equipment at the private automatic exchange end is caused to automatically function and thereby extend the trunked connection to a first available telephone in the private automatic exchange. In this connection it is to be borne in mind that a predetermined attendant's telephone in the private automatic exchange is to be normally the said first available telephone, but in case this telephone is engaged, by reason of it having been called through some other trunk terminating equipment accessible to it, or that it is engaged in a local or in an out trunked

connection, the trunk terminating equipment will select and seize a line leading to an alternative telephone, which latter may be in physical reach of the party answering calls at said first available telephone, or be at a remote location therefrom, responsive to a different party. The party at the called telephone responds by removing the receiver from the switch-hook, or by manipulating a key (equivalent to a switch-hook, but not shown) to include the telephone in series relation with the line leading thereto.

In the exemplified instance, the trunk terminating equipment at the private automatic exchange end of the trunk consists of two companion interlinked switching elements. One may be termed the main element and the other the auxiliary element thereto. The main element primarily automatically functions as a group selecting connector on its normal level consequent to the seizure of the trunk at the main exchange end. However, upon the releasing of its shaft to normal, without releasing its leading-in trunk at the main exchange end, the shaft of the said main element is thereafter capacitated to be operated vertically and then horizontally, directly.

It will now be assumed that a trunk has been seized at the main exchange end and that the main element at the private automatic exchange end of the trunk automatically extended the call to the first available telephone and signals it. The party thereat after responding, ascertains what local telephone is wanted. The said party will then manipulate the calling device of the telephone operative to the said auxiliary element, whereby the line extending to the desired telephone is seized (if not busy) and signaled upon. The said party may restore the shaft of the auxiliary element at any time before a response is obtained therethrough, directly, or in case the desired line is found busy to efface the extended connection and, if desired, extend the call to another telephone. The said party may retain connection until after a response is obtained, and in fact, remain in conference relation with the calling and last called party, unless directly released by the last called party, or by voluntarily replacing the receiver on the switch-hook. If the first called party replaces the receiver before a response is obtained, the said party may remove it and come in on the connection not responded to and re-communicate with the calling party in the main exchange. If desired, the shaft of the auxiliary element may be released and the call re-extended through it to some other telephone. However, if the wanted party responds, after the first called party has replaced his receiver, the shaft of the main element will thereby be restored to normal, disconnecting the first telephone reached. The main element, which

first functioned its shaft on its normal level, is now capacitated to function its shaft vertically and then horizontally responsive to the calling device of the telephone last called, and which was reached through the auxiliary element, and in general, operate like the auxiliary element, which does not have a normal rotary shaft movement under any condition.

If the calling party in the main exchange desires to directly extend the trunked connection as primarily extended to the first available telephone through the normal level of the main element, the said calling party will forthwith annex the digits corresponding to the wanted telephone, whereupon the auxiliary element will extend the connection thereto and apply signaling current. A novel feature of the present invention is a means for delaying the application of signaling current to a line first seized by the main element, so if the calling party in the main exchange immediately annexes the digits corresponding to the specific station in the private automatic exchange wanted, reached through the auxiliary element, the main element will be incapacitated against projecting signaling current before it is timed to project it. In any event, the first directive impulse applied to the auxiliary element incapacitates the main element against applying signaling current. The shaft of the main element is restored consequent to the specific station responding.

A means is provided for reversing the direction of current projected towards the main exchange from the line relay of the main element upon a first response being attained in the private automatic exchange, and this reversed condition is maintained until the shafts of both the main and auxiliary elements are restored to normal, regardless of the condition of any local line to which either element may be connected.

A means is provided wherein a tone source is briefly applied when a call has been passed and responded to, and the passing party has not replaced the receiver on the switch-hook before the response is obtained. This is to prompt the last responding party that a local station is in talking relation to the connection. A conference may proceed between the calling party in the main exchange, the passing party, and the last called party, or either one of the latter two may voluntarily replace the receiver on the switch-hook, or either of the local lines may be disconnected directly from the alternative local line, as desired, whereupon a brief tone will be again applied.

Calls originating at the private automatic exchange destined to a telephone in the main exchange are effected through the agency of a local connector operating as a selector on its "0" level, and there seizing a trunk to the main exchange. Upon the connector seizing,

the main element at the private automatic exchange end of the trunk selectively operates its shaft on its normal level and seizes the first set of bank contacts, which corresponds to the extension from the local connector. Then, upon a response of the called party in the main exchange, a relay disconnects the connector from the trunk and at the same time alternatively connects it to the trunk through the main element. It also causes the said trunk to be continued to the main and auxiliary elements in the private automatic exchange, so that in lieu of the primary connection from the "0" level of the local connector extending directly to the main exchange over the trunk, the trunk is now reached through the "0" level of the local connector and the normal level of the main element, and through the main element to the trunk. Upon the shafts of the main and auxiliary elements being restored, the trunk will be opened sufficiently long to restore the linking switches in the main office. If the called party in the main exchange disconnects first, the main or auxiliary element, or both of them, if off-normal, will be restored so that the operation so far as the users are concerned is essentially as if the call had been made to the private automatic exchange from the main exchange. The local telephones in the private automatic exchange are enabled to pass calls after gaining the response of the called party in the main exchange as if the call originated within the main exchange.

From the last foregoing, it will appear that a party at any telephone, perhaps at the instance of a party at some other telephone in the private automatic exchange, may call a telephone in the main exchange, and thereafter pass the connection to the telephone of the instructing party (or other telephone), from whence it may be further passed, as if the call had been an incoming call to the private automatic exchange primarily.

Means is provided so when a call is initiated at the private automatic exchange whereby the call from a telephone therein is directly extended to a first selector in the main exchange, and thereafter directly extended to a called station in the main exchange, if the called party in the main exchange terminates an established talking connection by replacing the receiver on the switch-hook thereat while the calling party still maintains the receiver at the calling station off the switch-hook, the trunk and linking apparatus in the main exchange will be restored to normal, and, therefore, a new call initiated at the main exchange can be forthwith extended over the said trunk, or any other available trunk, into the private automatic exchange. This, of course, will imply that the lineswitch terminating the trunk at the main office will not plunge-in under this condition.

The private automatic exchange equipment associated with the trunk line leading from the main exchange is generally adapted for use where the main exchange is operated manually rather than automatically directly over the trunk line from the private automatic exchange. It will thus appear that where a private automatic exchange is installed in connection with a manual main exchange and that the main exchange is later displaced by an automatic main exchange, only a slight circuit modification is necessary to adapt the trunk terminating equipment at the private automatic exchange to the changed method at the main exchange end of the trunk.

Where the private automatic exchange trunk is connected to a manual exchange, and a connection is directly established from the private automatic exchange over the trunk, and thence through an answering springjack and co-operating cord pair of the main exchange, and the service is terminated first at the main exchange end by the operator thereat withdrawing the switching plug from the trunk springjack, the connection will be destroyed and a false call will not occur at the main exchange end, and the trunk may be used forthwith for outgoing service from the main exchange.

Under the last above condition, clearing supervision will be afforded the operator at the main exchange, operative in the event the calling party from the private automatic exchange terminates the service first.

The foregoing specifically mentioned functions of the present invention and other functions and features thereof believed to be novel will be discussed hereinafter.

Referring to the drawings:—

Fig. 1 is a subscriber's telephone leading into a main exchange, together with a line-switch and a first and a second selector adapted to extend a connection in the direction of a called line. A connector adapted to complete a connection to the line leading to the said subscriber's telephone is shown, together with preceding selectors adapted to be inter-linked therewith in establishing the connection.

Fig. 2 shows a connector of the present invention and an incoming lineswitch associated with one of the lines accessible to the said connector.

Fig. 3 shows auxiliary apparatus at the private automatic exchange end of a trunk connecting the main exchange and the private automatic exchange.

Fig. 4 is a main element J of a pair of trunk terminating switch elements of the present invention.

Fig. 5 is an auxiliary element K to the said main element.

Fig. 6 is a connector which will function as a selector on certain levels, and has other

functions well known, as well as functions of the present invention.

Fig. 7 shows a portion of the main element J of Fig. 4 and two local telephones.

5 Fig. 8 shows a portion of the auxiliary element K of Fig. 5 and two local telephones and line switches therefor.

Fig. 9 shows the manner in which the accompanying sheets are assembled to display 10 the complete automatic system contemplated in the invention. The lines extending towards the margins and registering with lines on other sheets when placed in the indicated relation are to be assumed as continuations 15 of the same line, though not designated by reference characters, the latter being omitted where possible without obscuring the clearness of the complete disclosure, with due reference to the prior art and its relation- 20 ship to the devices of the present invention.

Fig. 10, which attaches to the left of Fig. 3, alternately with Fig. 2, shows well known manual exchange equipment such as has been 25 widely used in terminating private branch exchange trunks in main offices of manual systems, together with a well known switching cord pair Q adapted to connect with the trunk through a springjack and extend the 30 connection to or from the springjack of an accessible line.

Fig. 11 shows an alternative relay for excluding a resistance from the battery side of the trunk in lieu of reversing the trunk. In 35 the event the main exchange is manual, in lieu of automatic, the said Fig. 11 will be introduced in main element J of Fig. 4 where indicated by the section lines a, b, and c.

Fig. 12 shows the manner in which the accompanying sheets are assembled to display 40 the complete system contemplated in the invention under the alternative method of operation, wherein the main exchange is operated manually, in lieu of automatically, reference being made to the statements made 45 in connection with Fig. 9.

In embodying the present invention in a system as contemplated, apparatus elements are employed which are well known in the art. For example, the subscriber's telephone 50 (and others not shown) in the main exchange may be of the same class, and, in fact, of the exact type as the telephone designated A in U. S. Patent No. 13,901, re-issued to Frank Newforth, April 13, 1915. To extend a connection from telephone A in the direction of a called line, lineswitch C will function upon initiating the call and automatically extend the connection to first selector E. Upon manipulat- 55

60 telephone A in accordance with the first digit "1" of called number "1111" corresponding to the group of trunks to the private automatic exchange, the first selector E will operate responsive thereto and seize a trunk leading to second selector F. Upon operat- 65

ing the said calling device in accordance with the second digit "1", selector F will operate responsive thereto and seize a trunk leading to the connector G in Fig. 2. In order not to unduly involve the descriptions, the line- 70 switch C and the selectors E and F have been indicated rather than detailed, as well known forms of these elements may be employed. In fact, said C, E, and F may be of the exact types designated C, E, and F respectively in the said cited patent to Newforth.

Referring to Fig. 2, it will be clear presently that the connector G (which belongs to the general class as H of the said cited patent to Newforth) is a group-selecting connector controlled vertically and rotarily by directive impulses and which disassociates its operative circuits (line relay windings) from the normal bridge relation, consequent to the connector seizing. The connector G has access by first choice to a trunk of a group leading to a private automatic exchange, terminated by the equipments shown in Figs. 3, 4, 5, and 6. The said trunk is designed for two-way service in the present exemplified system, though it will be manifest that trunks employing the present invention may be reserved for one-way service only. The said trunk has a lineswitch C' permanently associated with it at the main exchange end. The 95 lineswitch will operate and automatically extend the trunked connection to first selector E' upon a conductive path being closed between the limbs of the trunk, or upon the battery side of the trunk becoming grounded 100 or applied to battery potential of the opposite polarity.

Upon the connection being extended from the private automatic exchange over the trunk to first selector E', operating a calling device whereby the series relation of the talking conductors of the trunk is interrupted one time in conformance with digit "1", the selector E' will operate responsive thereto and seize a trunk leading to second selector F', thus extending the connection to said F'. Again operating the calling device, but now in accordance with digit "2", the second selector F' will function by way of seizing a trunk leading to connector H'. Operating the calling device in accordance with the final two digits "1—1" will cause the connector to seize and signal upon the line leading to said A. While other well known forms of selectors, connectors, and lineswitches can be substituted for the said elements in Fig. 1, indicated only, in order to simplify the disclosure, the lineswitch C', selector E', selector F', and connector H', may be assumed of the exact types as C, E, F, and H, respectively, 110 in the said cited patent to Newforth.

Attention is directed to the fact that connector H in the said cited patent to Newforth causes the current projected over its leading-in line conductors to be reversed in direction 130

consequent to a response being obtained on the called line. That is, when the called party responds the current traversing the calling line is reversed in direction consequent thereto. This reversal of current may be used for supervisory and other uses, but it will appear presently, this condition is herein employed for the novel purpose of causing circuit changes affecting the relationship of the calling line to the trunk on calls outgoing from the private automatic exchange, to the main exchange.

In order to more conveniently correlate the elements in Figs. 1 and 2 to the corresponding elements in the said cited patent to Newforth, conductors and parts in Figs. 1 and 2 corresponding to conductors and parts in the said cited patent to Newforth will be similarly designated. In order to avoid confusion, designations with reference to E' and F' have a prime added.

Figs. 1 and 2 thus clearly disclose a main exchange system wherein a call may be initiated from a telephone therein and extended therefrom to a first selector automatically through the agency of a lineswitch, and then directly extended through a second selector to a group-selecting connector, and likewise through the said connector to a first available trunk of a group extending to a private automatic exchange system on the premises of a subscriber. Figs. 1 and 2 also clearly disclose a means of extending a connection, initiated over the said trunk and extended therefrom to a first selector automatically, through the agency of a lineswitch in the main exchange, and then directly extended through a second selector to a connector, and likewise through the said connector to a line leading to a telephone. In fact, Fig. 1, and also Fig. 2, with the exception of novel details and functions incorporated in connector G thereof, sets forth a well known organization of well known equipments constituting a main exchange system. The present invention is, however, particularly directed to a novel organization forming a private automatic exchange which is co-operative with the said well known organization constituting the main exchange, correlated through the agency of the novel connector G in the main exchange for calls destined to the private automatic exchange.

Referring to Figs. 4 and 5, the elements J and K are of the general class shown in Figs. 9 and 10, respectively, of British patent to Friendly (the present applicant) No. 139,000, the circuits of which are modified in accordance with the present invention.

Referring to Fig. 6, the connector L which is well known in the art, with the exception of certain holding features, as will appear, belongs to the general class as set forth in U. S. patent to Deakin, No. 1,164,479, granted December 14, 1915.

Referring to Figs. 7 and 8, the lineswitches M, N, O, and P, are of the general class as set forth in U. S. patent to Lamb, No. 1,193,160, granted August 1, 1916, and is well known in the art. The telephones or sub- 70 stations T7, T7', T8 and T8', are of the same class as A in Fig. 1.

To simplify the drawings and descriptions, the battery (which has its negative pole grounded), and ground are shown as independent sources throughout, wherever applied, but it is to be understood that the system is of the common battery type, and, therefore, one only or a lesser number of sources may be employed than indicated. In 75 the descriptions, when a circuit is traced to a winding, the opposite terminal of which is shown applied to grounded battery or to ground, the described circuit is to be considered as traced to ground through the winding and battery, or direct to ground, as indicated. In this connection, attention is directed to the connector H of the cited patent to Newforth, wherein line relay 16 has its battery winding normally connected to the conductor leading to condenser 30, and has its ground winding normally connected to the conductor leading to condenser 31, that is to say, conductor 58' and conductor 59' in Fig. 1 will normally have battery and 80 ground potential connected to them through a relay winding, respectively. It will be borne in mind that the said cited patent fully discloses that the above referred to battery and ground windings are reciprocated with 85 respect to the talking conductors leading in to the connector, incidental to a response being obtained on the called line.

The operation of this improved system will 90 now be described in general, by tracing and discussing its functioning under different 100 assumed operative conditions.

Assume a call from telephone A to the private automatic exchange, the telephone number of which is "1111". Upon the calling party initiating the call by removing the receiver 2 from the switch-hook 4 the lineswitch C will plunge-in and seize the first selector E. Upon sending the first digit "1", 110 constituted of one open impulse, the selector E will respond by stepping its wipers into alignment with the first level of bank contacts thereof and automatically rotate-in thereat and seize the first disengaged trunk 115 leading to second selector F. Upon sending the second digit "1" the selector F will respond by stepping its wipers into alignment with the first level of bank contacts thereof and automatically rotate-in thereat and seize the conductors 58, 91, and 59, leading to connector G. A circuit can now be traced from the upper winding of relay 201, make-before-break spring co-operative with armature 202, conductor 58, wiper 55, spring 44, spring 43, conductor 41, receiver 2, switch-hook 4, con- 120 125 130

ductor 42, spring 45, spring 46, wiper 56, conductor 59, make-before-break spring co-operative with armature 203, conductor 204 to the lower winding of relay 201, relay 201 actuating. A circuit can now be traced from the winding of slow-releasing relay 205 to grounded armature 206, relay 205 actuating. Armature 208 applies its ground to conductor 91 and maintains lineswitch C and selectors E and F seized in the well known manner.

Upon the calling party sending the third digit "1" relay 201 will deactivate and reactuate one time responsive thereto, armature 206 applying its ground to armature 209, series winding of slow-releasing relay 210, to the vertical magnet V2, sideswitch wiper 212 to grounded battery, relay 210 actuating and the vertical magnet stepping the wipers 213, 11', 12', and 13', into alignment with the first level of bank contacts thereof. At the time relay 210 actuated, armature 215 applied its ground to conductor 216, operatively energizing interrupter relay 217 and private magnet 218. Upon relay 210 deactuating, following the impulse to the vertical magnet, causing the armature of the private magnet 218 to retract, sideswitch wiper 212 and its companion sideswitch wiper 219 will be permitted to advance into their second position, the connector being now in readiness to receive the fourth digit. Upon the calling party sending the fourth digit "1" relay 201 will again deactivate and reactuate one time responsive thereto, armature 206 applying its ground to armature 209, series winding of relay 210, armature 220, winding of the rotary magnet R2, sideswitch wiper 212, to grounded battery, actuating the rotary magnet to step the wipers in one rotary position into engagement with bank contacts 221 to 224 (inclusive) respectively. Upon the relay 210 actuating, energized in series with the rotary magnet, the relay 217 and the private magnet 218 will be operatively energized in the manner as before set forth, and when the relay 210 deactuates following the impulse to the rotary magnet, the armature of the private magnet will retract, permitting the sideswitch wipers 212 and 219 to advance into their third position. A circuit can now be traced from grounded armature 206, sideswitch wiper 219, winding of slow-releasing relay 227, conductor 228, sideswitch wiper 212 to grounded battery, relay 227 actuating. The circuit path traced from the calling telephone A to talking conductors 58 and 59 is now continued from conductor 58, armature 202, winding of slow-releasing shunted relay 230, wiper 12', bank contact 223, conductor 84', armature 301, conductor 302, conductor 303, armature 304, make-before-break spring 305, conductor 306, make-before-break spring 401, conductor 402 to the upper winding of line relay 403, and from the lower winding of said relay, conductor 404, make-

before-break spring 405, conductor 406, armature 307, conductor 83', bank contact 224, wiper 13', armature 203 to conductor 59, relay 403 actuating. Relay 230 will be operatively energized from the current derived through relay 403 and will, therefore, apply the ground on working contact 232 to conductor 233, and through armature 334, conductor 335 to the winding of relay 205, before relays 205 and 227 have deactuated consequent to relay 201 deactuating resultant to armatures 202 and 203 on relay 227 attracting. Relay 205 being maintained actuated, maintains ground on conductor 91, however, the maintaining of ground on conductor 91 will depend upon the actuated condition of relay 230, which in turn, depends upon the continuity of the traced circuit including the windings of relay 403. That is to say, if the described circuit including the windings of relay 403 is opened, relay 230 will deactivate consistent with its slow-releasing characteristic, whereupon relay 205 will deactivate, removing the ground from conductor 91 and from the lower winding terminal of relay 227. Relay 227 is adjusted so it will deactivate after relay 205, and the relays maintaining lineswitch C and selectors E and F will also deactivate, causing the said C, E, and F, to restore in the well known manner. A circuit can now be traced from armature 208, spring 287 of off-normal set ON2 (which set operates on the first off-normal movement of the shaft) armature 238 to the release magnet Re2, the release magnet operating to restore the shaft of connector G to normal.

Assuming that at the time the wipers 213, 11', 12', and 13', engaged bank contacts 221 to 224 respectively, bank contact 222 constituted ground potential due to its corresponding trunk being busy by reason of the lineswitch C' being plunged-in, or because of the trunk having been previously seized by a switch having common access with G to the said trunk, it being clear that when a connector seizes and its conductor corresponding to 233 becomes grounded as described, the bank contact corresponding to 222 seized will constitute ground potential. The ground encountered by wiper 11' will be conducted over conductor 233, sideswitch wiper 219 to the outer winding of private 218, maintaining it actuated, notwithstanding relay 210 has deactuated, as described. Upon the relay 210 deactuating, followed by its dependent relay 217, a circuit can be traced from grounded armature 215, armature 240, armature 241 on the private magnet, armature 220, winding of the rotary magnet R2, sideswitch wiper 212 to grounded battery, the rotary magnet operating to drive the wipers 213, 11', 12', and 13', into engagement with bank contacts 243 to 246 respectively. At the time the rotary magnet operates, ground is applied to its armature and to conductor

216, causing relay 217 to actuate and interrupt the circuit traced energizing the rotary magnet and also to maintain the private magnet attracted. Upon the armature on the rotary magnet retracting, and relay 217 deactuating consequent thereto, the before traced circuit through the winding of the rotary magnet will become closed to ground on armature 215, provided bank contact 244 constitutes ground potential due to its corresponding trunk being busy, and in that event the said wiper set will be advanced into engagement with bank contacts 247 to 250 respectively, these being the bank contacts of the third trunk of a group of trunks extending to the private automatic exchange concerned. Assuming further that when the wipers have been advanced as last stated that bank contact 248 constitutes busy ground potential, bank contact 247 will likewise constitute ground potential, due to their being electrically tied together by tie conductor 251. At the time wiper 213 engages grounded bank contact 247 a circuit can be traced from grounded bank contact 247, wiper 213, conductor 252, make-before-break spring 253, conductor 254, armature 255, winding of relay 256, sideswitch wiper 212 to grounded battery, relay 256 actuating and locking through said spring 253, armature 258, conductor 259 to grounded off-normal spring 260. Relay 256 cannot unlock unless spring 260 is disengaged, which can only occur upon the shaft restoring to normal, and, therefore, the switch will not seize after relay 256 is actuated, notwithstanding ground is removed from bank contact 247 by reason of the trunk becoming idle. From the foregoing it is manifest that whenever wiper 213 encounters ground, the group selecting functioning of the connector G ceases, and by reason of armature 265 being attracted, ground-seeking busy tone from source T2 is applied to conductor 59, audible to the calling party.

From the foregoing description relating to connector G it is manifest that the said connector does not project ringing or signaling current to the seized trunk, nor does it supply talking battery to the called and the calling line as is usual in connectors. It will also be manifest that the connector G in its seized state involves no bridged attachments, and that the talking circuits thereof are clear, upon the connector seizing. Further, that the said connector is dependent upon other switch elements for its restoration to normal, all of which are novel so far as I am aware.

The system chosen to elucidate the present invention, so far as the private automatic exchange is concerned, involves a single trunk line, although it is to be understood that in commercial installations there would usually be a plurality of trunks terminating

in the private automatic exchange, each having equipments similar to the equipments on the trunk illustrated, so we are concerned chiefly with the trunk leading from the first set of bank contacts accessible to connector G, constituted of conductors 84' and 83'.

Going back to the condition of the circuits at the time relay 403 was described as actuating, a circuit can be traced from grounded armature 407 to the winding of slow-releasing relay 408, causing it to actuate. A circuit can now be traced from grounded armature 409, conductor 410, armature 411, conductor 412, winding of slow-releasing series relay 413, conductor 414, armature 415, winding of rotary magnet R4, conductor 416, armature 417, sideswitch wiper 418 to grounded battery, the rotary magnet operating to advance wipers 701 to 704 one rotary step into engagement with bank contacts 705 to 708 respectively. Incidental to this first rotary off-normal movement, off-normal springs RO4 operate. Also, the armature on the rotary magnet applies the ground on its working contact to conductor 419, operatively energizing interrupter relay 420, and the private magnet P4 by its outer winding.

At the time the rotary off-normal springs RO4 operate ground is applied through them to the winding of relay 421, causing it to actuate. A locking circuit can be traced from this winding, armature 422, conductor 423 to grounded armature 424 of actuated relay 408. At the time the armature of the rotary magnet R4 retracts, deenergizing relay 420 and the private magnet P4, sideswitch wiper 418 and its companion wiper 425 are permitted to advance into their second position. In this connection it will be noted that grounded armature 308 applies its ground through its resting contact to conductor 309 and to bank contact 706, engaged by wiper 702, and therefore, a circuit can be traced from the grounded bank contact 706, wiper 702, conductor 426, sideswitch wiper 425 to the inner winding of the private magnet P4, maintaining it energized, although the ground has been removed from conductor 419 incidental to the retraction of the armature on the rotary magnet R4.

A circuit can now be traced from grounded armature 427, armature 428, armature 429, conductor 414, armature 415, winding of rotary magnet R4, sideswitch wiper 418 to grounded battery, the rotary magnet operating to advance the wipers 701 to 704 a rotary step into engagement with bank contacts 709 to 712 respectively. It will be assumed that bank contact 710 does not constitute ground potential by reason of the line leading to telephone T7' being idle, and, therefore, the inner winding of private magnet P4 is deenergized, and the outer winding thereof is also deenergized by reason of the retraction of the armature on the rotary magnet R4 consequent to the rotary magnet

circuit being opened by the interrupter relay 420 at the time the rotary magnet armature attracted. The private magnet retracting permits the sideswitch wipers 418 and 425 to advance into their third position. A circuit can now be traced from ground, sideswitch wiper 425, conductor 426, wiper 702 to engaged bank contact 710, which will guard the line leading to telephone T7' against intrusion through other switches (not shown) having access to bank contacts multiply related to it. This ground can also be traced from sideswitch wiper 425, winding of seizing relay 430, sideswitch wiper 418 to grounded battery, relay 430 actuating by way of accomplishing the seizure of main element J. Interrupter I4 has a plunger with a retarded movement for closing the ringing circuit from source G4 to armature 431. That is to say, the said circuit from the source G4 is not closed for a predetermined period, which may be adjusted to suit conditions, after the winding of the interrupter I4 is energized. This latter winding will be energized consequent to the actuation of relay 408 incidental to the trunk to the private automatic exchange being seized, due to armature 424 grounding conductor 432. The period of retardation of interrupter I4, for example, would be five seconds under general operating conditions and, therefore, at the expiration of that period, which is a longer period than is required for the wipers 701 to 704 to have rotated the two steps into engagement with bank contacts 709 to 712, respectively, and, therefore, the ringing circuit will not be completed and operative for an appreciable time after the seizure, the object of which has been set forth in the general remarks at the outset and which will be discussed more in detail presently. The ringing circuit may be traced from source G4, left contact of interrupter, its short circuiting bar and the right contact, armature 431, armature 432, conductor 433, wiper 703, bank contact 711, conductor 714 through the ringer of the telephone set T7', conductor 715, bank contact 712, wiper 704, conductor 716, armature 434, armature 435, inner winding of ring-cut-off relay 436 to grounded battery. The current traversing the last traced circuit is operative to the ringer at telephone T7', but is inoperative to relay 436. Upon the response, wherein the receiver is removed from the switch-hook at telephone T7' a conductive path will ensue, operatively energizing the relay 436. A locking circuit can now be traced from grounded off-normal spring 437 of the off-normal set VR4 (which set operates on the first vertical or rotary off-normal movement of the shaft), armature 438 to the outer winding of relay 436. The said ground is extended over conductor 439 to the upper winding terminal of the lower winding of back-bridge relay 440. Armatures 431 and 435 being attracted, the traced circuit including the telephone T7' will now include conductor 441, lower winding of relay 440 to the traced ground, and from the upper winding terminal of relay 440, conductor 442 to armature 431, relay 440 actuating. A circuit can now be traced from grounded armature 443 to the slow-releasing relay 444, the latter relay actuating. Armature 445 applies its ground to conductor 446, which ground is communicated through armature 312, conductor 313, to the winding of reversing relay 447, causing the latter relay to actuate and reciprocate the relationship of the trunk conductors 84' and 83' with relation to the windings of relay 403, so that the current traversing the talking conductors of the trunk and the calling telephone will be reversed in direction. The said reversal has no operative object in the specific system described illustrative of the present invention, wherein the equipment at the main office, so far as the calling telephone is concerned, is not novel. However, well known equipment (and as referred to in the cited patent to Newforth) may be substituted for the calling telephone, or be an adjunct thereof, susceptible to current reversal, and under that condition may visually evidence to the calling party that a response has been obtained. The calling party at telephone A and the called party (the attendant) at telephone T7' are now in talking relation, conductors 402 and 442 being joined through condenser 442', and conductors 404 and 441 being joined through condenser 441'. Assume that the telephone T7' is busy when bank contact 710 is encountered by wiper 702, and bank contact 710 therefore constitutes ground potential received from a wiper corresponding to 702, for example, in the manner as hereinbefore described consequent to the seizure thereof. Under the last assumed condition a circuit can be traced from ground on bank contact 710, wiper 702, conductor 426, sideswitch wiper 425 in second position to the inner winding of the private magnet P4, maintaining the private magnet actuated after the retraction of armature 427, and, therefore, restraining the sideswitch wipers 418 and 425 from advancing into their third position. Interrupter relay 420 will deactivate following the retraction of the armature of the rotary magnet R4 resultant to the said relay 420 interrupting its circuit. A circuit can now be traced from grounded armature 427, armature 428, armature 429, conductor 414, armature 415, winding of the rotary magnet R4, sideswitch wiper 418 in second position to grounded battery, the rotary magnet operating to advance the wipers 701 to 704 an additional rotary step, in the manner as before described, the said wipers now engaging bank contacts 720 to 723, respectively. Assuming for the present that the telephone 120

T7 is idle, and that, therefore, bank contact 721 and its electrically tied contact 720 and their multiples accessible to other switches do not constitute ground potential, the main element J will seize in the manner as before described wherein the connection was effected to telephone T7'. The ringer 725 of telephone T7 will be vibrated in the manner as before described with relation to the call to telephone T7', and the said main element J will function as before described with relation to telephone T7' upon the receiver at telephone T7 being removed from the switchhook. The telephone T7 may be assumed as one of the general telephones of the private automatic exchange, and, therefore, may or may not be located within physical reach of the attendant, in fact, may be responded to by some other party located remotely. Inasmuch as the telephone T7 would only be reached by the main element J when operating on its normal level if the telephone T7' is busy, it serves as a supplemental attendant's station. As will appear presently, if the telephone T7 is also busy, the calling party at telephone A will receive a busy tone indicative of the busy condition. However, it will be manifest that an additional one or more telephones may be similarly related to telephone T7 with successive sets of bank contacts so that any one of a larger number than one telephone (as T7) may serve as auxiliary attendants' stations.

It will be assumed that when wiper 702 engages bank contact 721 that it and its tied contact 720 constitute ground potential due to the line leading to telephone T7 being busy. Upon wiper 701 encountering bank contact 720 a circuit can be traced from the said assumed grounded contact, wiper 701, conductor 448, make-before-break spring 449, armature 450, winding of busy relay 451, sideswitch wiper 418 to grounded battery, relay 451 actuating and locking through its armature 452 to grounded off-normal spring 437. The outer winding of the private magnet P4 is energized and locked to armature 452 by way of spring 453, and it will appear that relay 451 cannot unlock until off-normal spring 437 disengages, which can only occur when the shaft of the main element J restores to normal. During the time that relay 451 is actuated, ground-seeking tone source T5 is applied over conductor 501, through armature 454, to talking conductor 441, audible to the calling party at telephone A. The calling party being thus apprised of the busy condition, wherein the call will not be responded to, will replace the receiver on the switchhook, thereby opening the energizing circuit traced for relay 403, whereupon the latter relay and its dependent relay 408, will deactivate. A circuit can now be traced from grounded armature 424, conductor 456, off-normal spring 457 to the release magnet Re4,

the release magnet operating to restore the shaft carrying the wipers 701 to 704 to normal position, incidentally unlocking the relay 451.

Going back to the condition of the circuits when the calling party at telephone A was in talking relation with the party at telephone T7', it will now be assumed that the party wanted is at telephone T8, the local telephone number of which is "12". The attendant at telephone T7' will manipulate the calling device on the said telephone in accordance with the first digit "1", whereupon relay 440 will deactivate and reactuate one time responsive thereto. At the time of the said deactuation a circuit can be traced from grounded armature 443, armature 458 (relay 444 sustaining over the lapse) conductor 459, winding of slow-releasing series relay 502, winding of vertical magnet V5, sideswitch wiper 503 to grounded battery, the vertical magnet operating one time to raise the shaft carrying wipers 801 to 803 one vertical step into alignment with the first level of bank contacts. At the time the vertical magnet operates, relay 502 operates and applies ground from its armature 504 through make-before-break spring 505 to the winding of the private magnet P5, causing the said private magnet to operate preparatory to permitting the sideswitch wipers 503 and 506 to advance into their second position consequent to the retraction of armature 504 following the operation of the vertical magnet. In this connection it will be noted that upon the actuation of relay 502 its armature 508 applies ground to the inner winding terminal of relay 436, over conductor 439, which would cause the said relay to actuate and lock were it not in the present instance already locked. The object of the latter described function will appear presently. The attendant at telephone T7' will now manipulate the calling device thereat in accordance with the second digit "2", whereupon relay 440 will deactivate and reactuate two times responsive thereto, its armature 443 applying two ground impulses through armature 458, conductor 459, winding of relay 502, armature 509, winding of rotary magnet R5, sideswitch wiper 503 in second position, to grounded battery, the rotary magnet operating two times to advance the wipers 801 to 803 two rotary positions into engagement with bank contacts 805 to 807, respectively. The relay 502 actuates coincident with the first impulse applied to the rotary magnet R5 and sustains until after the second impulse terminates. When relay 502 actuated it reenergized the private magnet P5, preparing it to release upon the retraction of armature 504, to permit the sideswitch wipers 503 and 506 to advance into their third position, the latter, in this instance, occurring following the said engagement of bank contacts 805 to 807. A circuit can now be traced from ground, sideswitch wiper 506, winding

of relay 510, sideswitch wiper 503 to grounded battery, seizing relay 510 actuating by way of accomplishing the seizure of the auxiliary element K. The ringing circuit can now be traced from source G5, armature 512, armature 513, conductor 514, wiper 802, bank contact 806, conductor 810 through the ringer of telephone T8, conductor 811, bank contact 807, wiper 803, conductor 812, armature 515, armature 516 to the inner winding of ring-cut-off relay 517 to grounded battery, the ringer at telephone T8 vibrating responsive to the current from source G5, but the relay 517 is inoperative thereto. Upon the response where-
 5 in the receiver is removed at telephone T8 a conductive path will ensue, operatively energizing the relay 517. A locking circuit can now be traced from grounded off-normal spring 518 of the off-normal set VO5 (which
 10 set operates on the first vertical off-normal movement of the shaft), conductor 519, armature 520 to the outer winding of relay 517. The said ground is extended over conductor 521 to the upper winding terminal of the
 15 lower winding of back-bridge relay 522. Armatures 513 and 515 being attracted, the described circuit including the telephone T8 will now include conductor 523, lower winding of relay 522 to the traced ground, and
 20 from the upper winding of relay 522, conductor 524 to armature 512, relay 522 actuating. A circuit can now be traced from grounded armature 527 to the winding of slow-releasing relay 528, the latter relay actuating. Armature 529 applies its ground to conductor 446. The object of the latter function will appear
 25 presently. The talking circuit traced to conductors 406 and 306 is continued through armatures 460 and 461, conductors 462 and 463, and condensers 531 and 532 to conductors 524 and 523 respectively, so that telephones A, T7', and T8 are in talking relation
 30 mutually.

At the time the receiver was removed at telephone T8, and relay 528 actuated responsive thereto, bearing in mind that relay 444 was actuated due to the receiver being off the switch-hook at telephone T7', a circuit can be traced from grounded armature 535, conductor 536, armature 464, conductor 465 to the winding of interrupter I5. The interrupter I5 is designed to operate its plunger-arm 537 retardedly to link its contacts 538 and 539 for a brief predetermined period and
 35 then disengage them incidental to the continued upward stroke of the plunger-arm, so that under the conditions of the contacts 538 and 539 being linked the ground-seeking tone source T5' will be applied over conductor 540 to conductor 463 audible to the calling party at telephone A and also the first called party at telephone T7', as well as the second called party at telephone T8. As stated, this tone being applied for a predetermined brief
 40 period serves to prompt the party at telephone T8, who responded last, that not only is the calling party at telephone A in talking relation with said party at telephone T8, but that a telephone as T7', for example, is also in talking relation with said party at telephone T8, and the calling party at telephone A, mutually. It is manifest in view of the traced circuits that if the telephone T7' were not in on the connection the armature 464 would be retracted, and, therefore, the described circuit energizing the interrupter I5 would not have been energized to apply the tone T5', and, therefore, the last party to respond, in this case the party at telephone T8, would know that there is no third party in on the connection. Of course, in commercial systems it is frequently desirable to maintain three-party connections for conference, or for other reasons, and, therefore, it is desired that the prompting tone described shall not endure long enough to prove an annoyance. Under the conference condition, the contacts 538 and 539 are not linked due to the plunger-arm being fully attracted. However, should the party at telephone T7', or the party at telephone T8, terminate connection by replacing the receiver thereat, relay 444 or relay 528, as the case may be, will deactivate and open the described energizing circuit of the interrupter I5, whereupon its plunger-arm will retract somewhat faster than it originally attracted, and again link the contacts 538 and 539, however, more briefly than before, to apply the tone source T5' audible to the remaining two parties to the connection, thus apprising them that the third party to the connection has disconnected therefrom. While a battery click would undoubtedly be discerned incidental to the party disconnecting, this would not be positive information as would the specific tone.

In this connection attention is directed that when relay 447 actuated consequent to the party at telephone T7' responding, a locking circuit is established from the winding of said relay 447, armature 466, conductor 467 to grounded off-normal spring 468. It will be noted that conductor 469 is legged from conductor 467 and extends to spring 545 of off-normal set VO5, so that if the shaft of main element J has restored to normal and the shaft of auxiliary element K has operated off-normally beforehand the relay 447 is maintained locked through spring 545. The same would hold true, as will appear presently, wherein the shaft of main element J will operate off-normally in a second false operation before the shaft of auxiliary element K restores to normal, so that regardless of which element J or K has its shaft off-normal, or if both shafts are coincidentally off-normal, the relay 447 will be maintained locked. However, the relay 447 will become unlocked and deactivate, thereby establishing the primary relation of the leading-in con-

ductors 406 and 306 with the upper winding terminal and the lower winding terminal of relay 403, respectively, upon both the shaft of main element J and the shaft of auxiliary element K restoring.

Going back for a moment to the condition ensuing after the talking connection was established between calling telephone A and telephone T7' and wherein the party at telephone T7' caused the auxiliary element K to be directly operated therefrom to set its wipers 801 to 803 into engagement with bank contacts 805 to 807, respectively, by way of passing the connection. It will be assumed that after the last foregoing described operation was completed, and before a response was obtained from the party at telephone T8, as hereinbefore described, the party at telephone T7' replaced the receiver on the switch-hook. Relay 440 will deactivate by reason of its energizing circuit being open at the switch-hook of telephone T7' and its dependent relay 444 will deactivate in sequence. A circuit can now be traced from grounded armature 443, armature 458, to the winding of slow-releasing relay 470, the latter relay actuating. Then, upon armature 445 retracting immediately following the actuation of relay 470 and while relay 470 is still actuated due to its slow-releasing characteristic, a circuit can be traced from grounded armature 445, armature 471, conductor 472, armature 546, conductor 547, off-normal spring 457 to the release magnet Re4, the release magnet operating to restore the shaft of the main element J to normal. However, since the off-normal spring set VO5 is operated, relay 447 will be maintained locked and the telephone T8 will be signaled as before described wherein the party at telephone T7' retained connection, and the calling party at telephone A will be in talking relation with the last called party at telephone T8 upon the response thereto as in the instance before described, although in this instance the telephone T7' is not concerned, and, furthermore, the shaft of main element J is at normal, however, relays 447, 403, and 408 thereof are actuated, the relay 436 having unlocked incidental to the restoration of the shaft.

If, however, the party at telephone T7', in lieu of waiting until after the second digit "2" was sent and the relay 510 actuated to effect the seizure of the line leading to telephone T8, had replaced the receiver on the switch-hook before sending the second digit "2" and after sending the first digit "1", or at least replacing the receiver before the last impulse is sent and relay 510 actuates, a circuit is established from grounded armature 445, armature 471, conductor 472, armature 546, conductor 550, off-normal spring 551 to release magnet Re5 the release magnet operating to restore the shaft of auxiliary element K to normal. The party at telephone

T7 can forthwith directly operate the auxiliary element K to complete a connection to telephone T8, as before described, or to any other line, as primarily. The object of providing this function wherein the transferring party can efface a directed operation, wherein the operation has not progressed to a seizure, is to enable an error in calling a wrong digit, or otherwise, to be effaced.

Assume that the line leading to telephone T8 had been seized and rung upon, and perhaps no response obtained. In that event the relay 510 would be actuated. To effect the restoration of the shaft of auxiliary element K the party at telephone T7', will send digit "1" from the calling device thereat, whereupon relay 440 will deactivate and reactivate one time responsive thereto. Upon the said deactivation the relay 470 will be caused to activate as hereinbefore described, then upon the reactuation of relay 440, armature 476 will apply its ground to armature 477 before relay 470 deactuates, the said ground being continued over conductor 478, armature 552, conductor 550, off-normal spring 551 to the release magnet Re5, the release magnet operating as before, to restore the shaft of the auxiliary element K to normal.

Assume that at the time of calling telephone T8, as described, it is busy, and by reason of it having been previously engaged by a switch having access to it through one of the multiplied contact sets, or perhaps due to a call having been initiated outgoing from the said telephone T8, so that the bank contact 805 engaged by wiper 801 constitutes ground potential. A circuit can now be traced from the assumed grounded contact 805, wiper 801, conductor 553, sideswitch wiper 506 in second position, make-before-break spring 554, winding of relay 555, make-before-break spring 505 to the winding of private magnet P5, the private magnet being maintained actuated because this circuit ensues upon armature 504 retracting. Under this condition the sideswitch wipers 503 and 506 are restrained against advancing into their third position, and, therefore, an operative circuit for relay 510 is not established, so that the auxiliary element K does not seize. Relay 555 will actuate and lock by way of its armature 556 to grounded off-normal spring 518, and will be maintained locked until the shaft of the auxiliary element K restores to normal. Incidental to the operation of relay 555, busy tone is applied from source T5 over conductor 501, armature 557 to talking conductor 523, audible to the calling party at telephone A and to the passing party at telephone T7'. If it is desired to call an alternative telephone, the shaft of auxiliary element K can be restored by the party at telephone T7', sending digit "1", whereupon a ground will be applied to conductor 478, in the manner as before described, and continued

- through armature 558 (armature 552 being retracted) conductor 550, off-normal spring 551 to the winding of the release magnet Re5, the release magnet operating to restore the 5 shaft of auxiliary element K to normal, after which a new call may be directly extended as primarily, the tone source T5 being disassociated consequent to relay 555 becoming unlocked.
- 10 It will be assumed that after the talking connection was established from calling telephone A to first called telephone T7' and thereafter passed by the party at telephone T7' to telephone T8, and that a response is obtained at telephone T8, and that the receiver at the first called telephone T7' has been replaced on the switch-hook, leaving the shaft of main element J at normal and the calling party at telephone A and the last 15 called party at telephone T8 in talking relation, that it is now desired to re-pass the call to telephone T7, the telephone number of which is "11". Bearing in mind that relay 421 became actuated and locked to conductor 423 consequent to the first rotary off-normal movement of the main element J and that it is still in a locked condition, the party at telephone T8 will now operate the calling device thereat in accordance with the first 20 digit "1", whereupon the wipers 701 to 704 will be stepped vertically into alignment with the first (off-normal) level. This is accomplished by reason of relay 522 deactuating and reactuating one time responsive to the 25 said operation of the calling device at telephone T8, whereupon armature 527 applies its ground to armature 560, conductor 412, winding of relay 413, conductor 414, winding of vertical magnet V4, armature 417, side-switch wiper 418 to grounded battery, the 30 said vertical magnet operating to raise the shaft one vertical step as described. At the time relay 413 is energized from the last described impulse to the vertical magnet the 35 private magnet P4 is caused to actuate in the manner hereinbefore described, preparatory to permitting the sideswitch wipers 418 and 425 to advance into their second position, consequent to the deactuation of the said private 40 magnet upon the retraction of armature 427 following the said impulse. The said sideswitch wipers are now in their second position. Upon the party at telephone T8 sending the second digit "1", whereupon relay 522 45 will deactuate and reactuate one time responsive thereto, as before, armature 527 will apply its ground to armature 560, conductor 412, winding of relay 413, conductor 414, armature 415, winding of rotary magnet, 50 sideswitch wiper 418 in second position to grounded battery, the rotary magnet operating one time to advance the wipers 701 to 704 into engagement with bank contacts 727 to 730, respectively. Assuming that telephone T7 is not busy by reason of its line not 55

having been seized by a connector (as L) in access to it through a set of multiplied contacts, or that a call is not under way, initiated from the telephone T7, bank contact 728 and its tied contact 727 will not constitute ground potential. Under the latter condition, when armature 427 retracts, following the said impulse to the rotary magnet, the private magnet P4 will retract, permitting the sideswitch wipers 418 and 425 to advance into their third 70 position, whereupon a circuit can be traced from ground, sideswitch wiper 425, winding of relay 430, sideswitch wiper 418 to grounded battery, relay 430 actuating to effect the seizure of the main element J.

In this connection it will be recalled that the interrupter I4 is actuated and has its engaging contacts linked, and, therefore, immediately upon the seizure of main element J a circuit can be traced from source G4, 80 armature 431, armature 432, conductor 433, wiper 703, bank contact 729, ringer 725 of telephone T7, bank contact 730, wiper 704, conductor 716, armature 434, armature 435, inner winding of relay 436 to grounded battery, the ringer 725 vibrating, and the relay 436 remaining normal due to its characteristic referred to hereinbefore. Upon the response of the party at telephone T7 by removing the receiver from the switch-hook 90 thereat, the relay 436 will be operatively energized in a manner as hereinbefore described, and it will lock to grounded off-normal spring 437. In the manner as hereinbefore described, relay 440, and its dependent 95 relay 444, will actuate consequent to the actuation of relay 436, so that the calling party at telephone A, the party at telephone T8, and the last called party at telephone T7, are in 100 talking relation, mutually.

In this connection attention is directed that the interrupter I5 deactuated at the time its energizing circuit was open at armature 464, and that it is now reenergized due to the said armature re-attracting, whereupon the 110 tone source T5' is applied in the manner as hereinbefore described, audible to the three parties to the connection, and if either party at telephone T8 or T7 disconnects from the connection, the interrupter I5 will deactivate, and will cause a brief tone to be applied 115 audible to the remaining two parties of the connection upon the plunger-arm 537 retracting into engagement with contacts 538 and 539 in the manner, and with the object, as 120 hereinbefore described.

Assume that party at telephone T8 replaces the receiver on the switch-hook, whereupon relay 522 and its dependent relay 528 will deactuate in sequence, relay 565 being energized 125 and actuates after armature 527 retracts and before armature 560 retracts. Due to the slow-releasing characteristic of relay 565 a circuit will be closed from grounded armature 529, armature 566, conductor 567, arma-

ture 479, conductor 550, off-normal spring 551 to the release magnet Re5, the release magnet operating to restore the shaft of auxiliary element K to normal.

- 5 Assume that instead of the party at telephone T8 replacing the receiver in order to effect the said restoration of auxiliary element K, the party at telephone T7 wished to do this directly. The party at telephone T7 would 10 operate the calling device in accordance with digit "1", whereupon relay 440 would deactivate and reactuate one time responsive thereto, the relay 470 actuating consequent to the retraction of armature 443, in the manner as 15 hereinbefore described. Then, upon the said re-attraction of relay 440 a circuit will be established from its grounded armature 476, armature 477, conductor 478, armature 552, conductor 550, off-normal spring 551 to the 20 release magnet Re5, the release magnet operating to restore the shaft of auxiliary element K to normal.

Assume that the party at telephone T8 wishes to directly restore the main element 25 J, disassociating the telephone T7 from the three-party connection. The party at telephone T8 will operate the sending device thereat in accordance with the digit "1", whereupon the relay 522 will deactivate and 30 reactuate one time responsive thereto. At the time armature 527 retracts, relay 565 will be caused to actuate in the manner as hereinbefore described. Then, upon the said re-attraction of relay 522 a circuit will be established from its grounded armature 570, armature 571, conductor 572, armature 480, conductor 456, off-normal spring 457 to the 35 release magnet Re4, the release magnet operating to restore the shaft of the main element J to normal, bearing in mind that due to the shaft of the auxiliary element K being off-normal, the relay 447 will remain locked, and that due to armature 424 being attracted, the relay 421 will remain locked.

- 40 It will be assumed that at the time wiper 701 first engaged bank contact 727 it encountered ground potential thereon due to the telephone T7 being busy. A circuit can be traced from the assumed grounded contact 45 727, wiper 701, conductor 448, make-before-break spring 449, armature 450, winding of relay 451, conductor 416, sideswitch wiper 418 in second position to grounded battery, the relay 451 actuating and locking in the 50 manner as hereinbefore described, and the tone source T5 will be applied to conductor 441 audible to the calling party at telephone A and the party at telephone T8, in a manner as hereinbefore described. The party at 55 telephone T8 can now restore the shaft of the main element J by manipulating the calling device on the said telephone in accordance with the digit "1", whereupon relay 522 will deactivate and reactuate one time responsive thereto, and wherein relay 565 will be caused

to actuate in a manner as hereinbefore described. While relay 565 is actuated, and after armature 570 re-attracts, a circuit can be traced from grounded armature 570, armature 571, conductor 572, armature 481, conductor 456, off-normal spring 457 to the release magnet Re4, the release magnet operating to restore the shaft of main element J to normal. As in the last foregoing instance, where the shaft of main element J was directly restored, the main element J can be forthwith directly operated to effect a connection to any accessible line, under directive control of the calling device at telephone T8.

Attention is directed to the fact that the bank contacts 727 and 728 are electrically tied, and that the office of bank contact 727 is solely to cause the busy tone to be applied, if the line leading to telephone T7 is busy. Considering for a moment that the tie conductor 735 is removed and that, therefore, bank contact 727 does not constitute ground potential under the condition of bank contact 728 constituting ground potential. At 40 the time that wiper 702 engages assumed grounded bank contact 728 this ground will be communicated over wiper 702, conductor 426, sideswitch wiper 425 in second position, to the inner winding of private magnet P4, 45 maintaining the private magnet actuated, and thus restraining the sideswitch wipers 418 and 425 from advancing into their third position in a manner as hereinbefore described with relation to wiper 702 engaging 50 bank contact 706 assumed to be grounded. Upon the relays 413 and 420 deactuating, armature 427 applies its ground to armature 428, armature 429, conductor 414, armature 415, winding of rotary magnet R4, sideswitch 55 wiper 418 in second position to grounded battery, the rotary magnet operating to advance the wipers an additional rotary position. This cycle of operations concerning the rotary magnet R4 will continue as long as 60 wiper 702 engages a grounded bank contact, or until wiper 701 engages a grounded bank contact in the manner as hereinbefore described with relation to the normal level. It is thus manifest that groups of lines may be 65 employed in levels other than the normal level, accessible to the wipers of the main element J, and that these lines will be successively tested and the first idle one thereof seized, following the directive selection of 70 the first set of bank contacts corresponding to the first line of the group. However, in the illustration, the lines of the first level, of which the one leading to telephone T7 is the first, are arranged as independent lines.

Assume that the connection between telephone A and telephone T7 exists, and that the shaft of the auxiliary element K is at normal, it having been restored directly from the telephone T7, or by reason of the 130

party at telephone T8 replacing the receiver. It will next be assumed that it is desired to pass the connection to telephone T8', the telephone number of which is "13". The party at telephone T7 will manipulate the sending device thereat in accordance with the digits "1-3" in successive order, whereupon relay 440 will deactivate and reactuate responsive thereto, and cause the vertical magnet V5 to step the wipers 801 to 803 into alignment with the first level of bank contacts, and then rotated three steps into engagement with bank contacts 815 to 817, respectively, and thus effecting connection to the line conductors extending to telephone T8', and including the ringer 818. Auxiliary element K will seize, and ringing current applied from source G5 in a manner similar to that described with relation to calling the telephone T8. Upon the party at telephone T8' responding by removing the receiver from the switch-hook, the auxiliary element K will function corresponding to its functioning hereinbefore described with relation to the response at telephone T8.

Assuming that the party at telephone T7 replaces the receiver on the switch-hook, relays 440 and 444 will deactivate in sequence responsive thereto, and relay 470 will be caused to actuate in the manner as hereinbefore described. After relay 444 deactuates, and before relay 470 deactuates, a circuit can be traced from grounded armature 445, armature 471, conductor 472, armature 546, conductor 547, off-normal spring 457 to the release magnet Re4, the release magnet operating to restore the shaft of main element J to normal.

Assume that the party at telephone T8' replaces the receiver on the switch-hook in lieu of party at telephone T7, relays 522 and 528 will deactivate in sequence responsive thereto, and relay 565 will be caused to actuate in the manner as hereinbefore described. After relay 528 deactuates, and before relay 565 deactuates, a circuit can be traced from grounded armature 529, armature 566, conductor 567, armature 479, conductor 550, off-normal spring 551 to the release magnet Re5, the release magnet operating to restore the shaft of auxiliary element K to normal.

The shafts of main element J and auxiliary element K are assumed restored to normal, the locking circuit for relay 447 will be open, since conductor 469 does not now constitute ground potential. However, the relay 421 is still locked to armature 424.

The armature 482 is introduced to enable the calling party at telephone A to directly operate the auxiliary element K. For example, should it be desired to call telephone T7 from telephone A after the stated restoration of the shafts of main element J, and auxiliary element K, the party at telephone A

will manipulate the calling device thereat in accordance with the first digit "1", whereupon relay 403 will deactivate and reactuate one time responsive thereto, armature 407 applying its ground to armature 483, armature 482, conductor 459, winding of relay 502, winding of vertical magnet V5, sideswitch wiper 503 to grounded battery, the vertical magnet operating as hereinbefore described, functioning to step the wipers 801 to 803 one vertical step into alignment with the first level of bank contacts, the private magnet P5 operating in the manner as before described, to permit the sideswitch wipers 503 and 506 to advance into their second position, following the said impulse to the vertical magnet. Upon the calling party sending the second digit "1", relay 403 will again deactivate and reactuate one time responsive thereto, and apply a ground impulse over the traced circuit including the winding of relay 502, but this time by way of armature 509, winding of rotary magnet R5, sideswitch wiper 503 in second position to grounded battery, the rotary magnet operating to advance the wipers 801 to 803 one rotary step into engagement with bank contacts 820 to 822, respectively.

Assume that telephone T7 is not busy, and, therefore, bank contact 820 does not constitute ground potential, the private magnet P5 will deactivate and permit the sideswitch wipers 503 and 506 to advance into their third position, so that the element K will seize and apply ringing current over conductors 825 and 826 effective to the ringer 725 of telephone T7, in a manner as hereinbefore described. Upon the party at telephone T7 responding by removing the receiver from the switch-hook, relay 517 will actuate, followed by relays 522 and 528, whereupon the calling telephone A and the called telephone T7 are in talking relation. The calling party at telephone A can release the shafts of both main element J and auxiliary element K by replacing the receiver thereat on the switch-hook, causing relay 403 and its dependent relay 408 to deactivate in sequence. A circuit will then be closed (provided the shaft of main element J is off-normal) from grounded armature 424, conductor 483, off-normal spring 551 to the release magnet Re4. If the shaft of auxiliary element K is off-normal a circuit will be then closed from grounded armature 424, off-normal spring 551 to the release magnet Re4.

In the foregoing descriptions nothing has been specifically mentioned with relation to the functioning of the lineswitches M, N, O, and P, these lineswitches being well known in the art, and, therefore, are not a part of the present invention in themselves, but only in their relation to the general organization of the system. It, however, may be stated that at the time conductors 740, 741, 830, and 831

became grounded, respectively, consequent to a corresponding bank contact becoming grounded incidental to the seizure of main element J or the auxiliary element K (or from connector L, as will appear, presently) when wiper 702 or wiper 801 is in engagement with a said contact, respectively, the said wipers become grounded from its element incidental to the said seizure. When main element J seizes, from its sideswitch wipers advancing into their third position, it applies ground to conductor 426 leading to wiper 702, and when the auxiliary element K seizes, from its sideswitch wipers advancing into their third position, it applies ground to conductor 553 leading to wiper 801. The grounding of a conductor 740, 741, 830, and 831 causes a corresponding relay 742, 743, 832, and 833 to be actuated, respectively, therefrom, which function serves to disassociate attachments from the talking conductors relating to telephones T7, T7', T8, and T8', respectively.

Assume that at the time telephone T7' was first signaled upon, resultant to the trunk line to the private automatic exchange being seized by connector G, and the main element automatically initiated a rotary movement and seized a line leading to the said telephone T7', the calling party desired to attain connection with some other telephone as T8, for example. Bearing in mind that ringing current is not applied from the main element J for a predetermined time, if the calling party at telephone A forthwith manipulates the calling device thereat in accordance with the first digit "1" of the telephone number of said T8, relay 403 will deactivate and reactuate one time responsive thereto, whereupon its armature 407 will apply ground to armature 483, armature 482, conductor 459, winding of relay 502, winding of vertical magnet V5, sideswitch wiper 503 to grounded battery, the vertical magnet operating to step the wipers of auxiliary element K into alignment with the first level of bank contacts. Incidental to the actuation of relay 502, ground is applied through its armature 508, conductor 439, to the inner winding of relay 436, causing the latter relay to actuate and lock, as has been referred to hereinbefore. The actuation of relay 436 serves to disassociate the conductor leading to the resting contact of armature 431, and, therefore, prevents ringing current being applied to the seized line leading to telephone T7'. If, at the time the main element J rotated on its normal level, it failed to encounter a disengaged line, and, therefore, operated in the manner as hereinbefore described, wherein it projected a busy tone audible to the calling party at telephone A, this busy tone would be ignored and the said first digit "1" would be sent forthwith as described, causing the described operation of the auxiliary ele-

ment K, regardless of the busy conditions encountered by the main element J. Of course, the main element J would not seize under the last assumed condition, and, therefore, the energizing of relay 436 under control of relay 502 would be to no operative purpose. 70

Upon the calling party sending the last digit "2" of the telephone number of telephone T8, relay 403 will deactivate and reactuate two times responsive thereto, its armature 407 applying two ground impulses to armature 483, armature 482, conductor 459, winding of relay 502, armature 509, winding of rotary magnet R5, sideswitch wiper 503 in second position (the sideswitch wipers 503 and 506 having been permitted to advance from their first position consequent to the retraction of armature 504 following the application of the impulse to the vertical magnet V5, in the manner as hereinbefore described) 80 to grounded battery, the rotary magnet operating to advance the wipers 801 to 803 into engagement with bank contacts 805 to 807, respectively. The functioning of auxiliary element K in seizing the line leading to telephone T8, if it is idle, and if it is not idle, to project a busy tone, audible to the calling party, will be the same as described, wherein the auxiliary element K was operated to effect a connection to said telephone T8 directly, controlled from telephone T7'. Assume that telephone T8 was not busy and that the auxiliary element K seizes and applies ringing current, and that the party at telephone T8 responds, relays 522 and 528 100 will actuate in sequence in the manner as hereinbefore described. A circuit can now be traced from grounded armature 529, conductor 446, armature 312, conductor 313 to the winding of relay 447, the latter relay actuating and locking through its armature 466, conductor 467, conductor 469, off-normal spring 545 to ground. The direction of current transversing the trunk conductors 84' and 83' will be reversed, as hereinbefore described, due to the actuation of relay 447. A circuit can also be traced from grounded armature 535, conductor 536, armature 464, vertical off-normal contacts VO4 (off-normal contacts VO4 being adjusted to open on the first vertical off-normal movement of the shaft, and not operate on the-off-normal movement at the normal level), off-normal spring 457 to the release magnet Re4, the release magnet operating to restore the shaft of main element J to normal, preparatory to being directly operated by way of passing the connection to any other line in access thereto; the line leading to telephone T7, for example, 120 the operation being as before described. The calling telephone A and the called telephone T8 are now in talking relation, the circuits and equipment elements thereof being as when the said talking connection was as 125

sumed established in the descriptions hereinbefore.

From the foregoing, it is clear that upon the calling party attaining connection with a trunk leading to the private automatic exchange, the main element J will automatically initiate its functioning by way of rotating its wipers on its normal level and seize the line leading to an attendant's or other responding telephone, and that the responding party can then directly pass the connection to a third telephone, etc. Also, that in the event the calling party at telephone A desires to directly attain connection with a specific telephone in the private automatic exchange, the calling device at the calling telephone can be manipulated in accordance with the telephone number of the desired telephone, and the wipers of the auxiliary element K will be thereby set upon the bank contact set corresponding to the said telephone, and the latter telephone signaled, or that a busy tone will be applied audible to the calling party if the said latter telephone is busy, the telephone automatically connected with, through the main element J, not being signaled, by reason of the ringing current applied to the said main element J being directly disassociated by the calling party consequent to the first directive impulse being applied after the trunk is seized by connector G, and furthermore, that the shaft of main element J is caused to be restored consequent to a response being attained from the said specifically directly called telephone. The said restoration of the shaft of main element J upon the response of the party called through auxiliary element K only applies under the specific operative condition last described, due to the adjustment of the off-normal set VO4.

It will now be assumed that a call is directly extended to a called telephone A in the main exchange from a local telephone T7, for example, and that after a response is attained the connection at the private automatic exchange will be passed to telephone T8, for example, the latter being accomplished as if the call were primarily an incoming call to the private automatic exchange, and that the telephone T7 was automatically reached or was subsequently reached through a passing operation, as has been set forth hereinbefore.

It will be noted that the lineswitches M, N, O, and P, have a common relation through corresponding bank contacts thereon, respectively, with trunk conductors 750, 751, and 752 leading to the connector L, which connector normally functions as a connector, but which functions as a selector on its tenth or "0" level, the co-operating levels shown being the first and "0" levels. The said lineswitches M, N, O, and P being well known in the art, their operation will not be de-

tailed. Suffice it to say, however, that upon the calling party at telephone T7 removing the receiver from the switch-hook the line-switch M will seize and extend the connection to connector L. Of course, had the wipers of lineswitch M been resting on the bank contacts of a busy connector trunk it would automatically function and advance the said wipers to a first idle set of bank contacts, which may be assumed as those of the trunk leading to connector L. In a commercial installation the lineswitches would usually have access to ten or more connectors similar to L, so that any number of telephones, one hundred for example, would have access to all of a common group of connectors similar to L, one such connector being shown. The complete functioning of the connector L will not be detailed, since it is well known in the art (with the exception of novel functions involved in wiper 615 and the upper winding of relay 619, as will appear presently), however, it may be stated, that through the first level it has access to the same telephones as elements J and K through corresponding bank contact sets similarly disposed numerically, so that the telephones of the private automatic exchange can inter-connect locally, as has been a common practice.

At this juncture a circuit can be traced from the upper winding of relay 601, make-before-break spring 602, conductor 751, bank contact 755, wiper 756, armature 757, through the telephone T7, armature 758, wiper 759, bank contact 760, conductor 750, make-before-break spring 603, to the lower winding of relay 601, the said relay actuating. A circuit can now be traced from grounded armature 605, conductor 606, armature 607, to the winding of slow-releasing relay 608, the said relay actuating. A circuit can now be traced from grounded contact 609 to conductor 752, the said ground serving to sustain the lineswitch M in a seized condition, in the well known manner.

The listed telephone number of called telephone A is "2111", and, therefore, it is necessary for the calling party at telephone T7 to first call "0" by manipulating the calling device thereat in accordance therewith, effectuating ten open impulses constituted thereof. Relay 601 will deactivate and reactivate ten times responsive thereto, and upon each retraction of its armature 607 its ground will be applied to armature 612, sideswitch wiper 613 (relay 608 sustaining over the lapses), winding of slow-releasing relay 614, winding of vertical magnet V6, sideswitch wiper 615 to grounded battery, the vertical magnet operating ten times to step the wipers 615 to 618 into alignment with the "0" bank level. Off-normal contact set ON6 operates on the first off-normal movement of the shaft of the connector; off-normal contact set n6 operates upon the shaft of the connector at

taining the 9 level; off-normal set t_6 operates upon the shaft of the connector attaining the "0" level. Upon the retraction of armature 620, following the last impulse to the vertical magnet, whereby the private magnet P6 deenergizes, permitting the sideswitch wipers 613, 615, and 621 to advance into their second position, whereupon, due to relay 622 being actuated, due to the off-normal set n_6 being operated, the rotary magnet R6 will be energized over a circuit completed from grounded armature 605, and lower armature of relay 622, the wipers being driven a rotary step into engagement with bank contact set 624 to 627, seeking an idle trunk to seize, all in the well known manner. At the time the rotary magnet operates, its armature mechanically closes the escapement armature of the private magnet, thus retaining the said sideswitch wipers from advancing into their second position. It will be assumed that the first set of bank contacts 624 to 627 leading to conductors 358, 628 to 630, respectively, are idle. Bank contact 625, therefore, constitutes battery potential derived through the relay 328. Upon the retraction of the rotary magnet, the private magnet will not be sustained, as it would be if the bank contact 625 constituted ground potential, so the said sideswitch wipers are released to advance into their third position, whereupon the inner winding of relay 632 will be energized from the battery on bank contact 625 to the ground on the electrical armature on private magnet P6, the relay 632 actuating and locking its outside winding through armature 633, conductor 634 to grounded contact 609, and due to relay 622 being actuated, the relay 623 will actuate from its winding being closed through off-normal set t_6 , armature 635 to armature 633, the connector, therefore, having seized, the windings of relay 601 being disassociated. However, due to the actuation of shunted series relay 619 because of its lower winding being energized, as will appear presently, armature 636 applies its ground to the winding of relay 608, maintaining it, dependent upon relay 619 remaining actuated.

Wiper 616 applies ground to bank contact 625 consequent to sideswitch wiper 621 advancing into its third position incidental to the seizure of connector L, in the well known manner, so that a circuit can now be traced from grounded contact 609, conductor 634, armature 633, spring 637, sideswitch wiper 621, wiper 616, bank contact 625, conductor 628, armature 325, conductor 326, armature 327 to the winding of relay 328, said relay actuating. A circuit can now be traced from the upper winding of relay 403, conductor 402, make-before-break spring 401, conductor 306, armature 329, armature 330, make-before-break spring 331, conductor 406, make-before-break spring 405, conductor 404 to the lower winding of relay 403, relay 403 actuating, followed by the actuation of its dependent relay 408. The main element J having been at normal, the hereinbefore described functioning of said main element J will ensue as wherein it automatically initiated its rotary functioning on the normal level consequent to the actuation of relay 403, when seized by connector G, and a closed circuit including conductors 306 and 406 was formed, as was (though over a different path) in the last described functioning. It will be noted in this connection, that due to relay 328 being actuated ground has been removed from conductor 309 leading to bank contact 706, and, therefore, the bank contact set 705 to 708 is unguarded and will be seized upon the wipers 701 to 704 engaging them, and the said wipers will, therefore, not progress and seize one of the lines leading to local telephones T7' or T7, for example. Ringing current will be applied to conductors 762 and 763, but to no operative purpose since they are open at armatures 332 and 333, respectively. A circuit can also be traced at this juncture which will include the lower winding of relay 619 and the winding of the line relay of the lineswitch C', causing the latter to function in the well known manner, and plunge-in and seize the trunk leading to the first selector E', whereupon a circuit can be traced from the upper (battery) winding of the line relay of said selector E' over conductor 120, lineswitch spring 121, trunk conductor 84', series winding of electro-polarized relay 334, conductor 302, conductor 303, armature 338, make-before-break spring 335, conductor 629, bank contact 626, wiper 617, lower winding of shunted relay 619, armature 640, conductor 641, armature 642, make-before-break spring 602, conductor 751, bank contact 755, wiper 756, armature 757, through the telephone T7, armature 758, wiper 759, bank contact 760, conductor 750, make-before-break spring 603, armature 643, conductor 644, armature 645, wiper 618, bank contact 627, conductor 630, make-before-break spring 336, conductor 83', lineswitch spring 122, conductor 123, to the lower (ground) winding of the line relay in selector E'. Relay 619, which has the characteristic of sustaining over impulse lapses, thus remains energized dependent upon the sustained continuity of the traced circuit including the telephone T7. Should the receiver be replaced on the switch-hook of the telephone T7, (bearing in mind the call has not been completed), causing relay 619 to de-actuate, dependent relay 608 will de-actuate in sequence and the ground will be removed from conductor 752 which will cause the lineswitch M to terminate its seizure, in the well known manner. A circuit can be traced from grounded armature 605, armature 607, armature 612, off-normal spring 648 to the release magnet Re6, the release magnet operating to

restore the shaft of connector L to normal, in the well known manner.

Continuing the description with relation to the connection extended from calling telephone T7 to first selector E', upon the calling party at telephone T7 manipulating the calling device thereat in accordance with the first digit "2", the selector E' will function, in the well known manner, and extend the connection to second selector F', and upon the second digit "1" being sent, the said selector F' will function, in the well known manner, and extend the connection to connector H'. Upon the last two digits "1-1" being sent, the connector H' will function, in the well known manner, to set its wipers 11 to 13 on the bank contacts of the line leading to called telephone A and to operate the line cut-off relay of the line switch C associated with the line leading to called telephone A, and signal telephone A, all in the well known manner and in view of the cited patent to Newforth.

Upon the called party at telephone A responding, the current projected from the front-bridge or line relay of the connector H' will be reversed in direction, so the current traversing the series winding of relay 334 will now flow in the opposite direction to that originally established. In this connection it will be understood that at the time relay 328 actuated a circuit was established from the polarizing winding of relay 334, armature 340, armature 341 to its grounded working contact, and that the current traversing this winding will magnetize the core of relay 334 in the opposite direction from that traversing the series winding thereof, when the current was primarily established through it. However, its armature 342 is marginally adjusted to be inoperative until both windings of relay 334 energize cumulatively, as ensues upon the party at telephone A responding, and the connector H' reverses the direction of current projected from it over the calling trunk, as set forth. The adjustment of relay 334 is such that after its armatures attract, the current in the series winding thereof will maintain it actuated, although no current traverses its inner electro-polarizing winding, and it will deactivate retardedly due to its mechanical design and the fact of the short-circuit applied at armature 301, upon relay 328 deactuating, as will appear presently.

Incidental to the attraction of armature 342 consequent to the response of the called party at telephone A, a circuit can be traced from grounded working contact and its armature 342, make-before-break spring 345 to the winding of relay 346, causing it to actuate and lock through its lower armature to conductor 469 which became grounded to off-normal spring 468 consequent to the first off-normal movement of the shaft of main

element J. In this connection it will be noted that relay 346 will remain locked until conductor 469 becomes ungrounded, which will only occur, as has been fully explained hereinbefore, when the shafts of the main element J and the auxiliary element K have been restored to normal. A second energizing circuit leads from armature 342 to the winding of switching relay 347, causing the latter relay to also actuate and lock 75 through its armature 348; conductor 432 to grounded armature 424, and will be maintained locked until relay 403 deactuates, and the latter is now controlled from either the main exchange or the private automatic exchange. Due to armature 327 being attracted, the energizing circuit of relay 328 will be opened, causing it to deactivate. Relay 334 will deactivate upon armature 340 attracting, its series winding being short-circuited by armature 301, following the attraction of armature 327. At the time relay 334 actuates and after armature 349 attracts, a circuit can be traced from the terminal of the lower winding of relay 353, armature 344, armature 349, conductor 406, spring 405, conductor 404 to ground through lower winding of relay 403, the latter relay being already actuated, energized over the trunk, as described. However, during the brief 95 time armature 344 is attracted, the ground derived through the lower winding of relay 403 is communicated to the lower winding of relay 353, causing it to actuate and lock its upper winding through armature 354, conductor 628, bank contact 625, wiper 616, sideswitch wiper 621, armature 633 to grounded conductor 634, relay 353 being thus maintained, dependent upon receiving ground from conductor 628. 105

A circuit can now be traced from trunk conductor 84', armature 301, conductor 302, armature 350, armature 351, make-before-break spring 305, conductor 306, make-before-break spring 401, conductor 402 to the upper (battery) winding of relay 403, and from the lower (ground) winding of relay 403, conductor 404, make-before-break spring 405, conductor 406, armature 307 to conductor 83'. In view of the reversed current projected back over the trunk, the battery winding of the line relay of the connector H' at the main exchange will operate in series with the ground winding of the said relay 403, and the battery winding of the said relay 403 will operate in series with the ground winding of the line relay of the said connector H', the said relays, therefore, remaining actuated. 115

By reason of armatures 332 and 333 being 125 attracted, the trunk conductors 629 and 630 leading-out from the contacts 626 and 627 seized by connector L are disassociated from conductors 84' and 83' and associated with conductors 762 and 763, respectively. The 135

said conductors 762 and 763 having been seized by the main element J, relay 436 will operatively energize over the traced circuit including the lower winding of the series relay 619 and telephone T7 and apply the upper and lower windings of relay 440 to the conductors 762 and 763 respectively. That is to say, the telephone T7 is now energized from the current derived through the upper and lower windings of relay 440, and the talking connection completed to the trunk conductors 84' and 83', respectively, over the traced circuits, and that the main element J is related to conductors 84' and 83' in the same effective circuit relation as when the call originating at the main exchange was completed to the main element J and the line leading to telephone T7' was automatically seized.

It will now be assumed that the party at telephone T7 replaces the receiver on the switch-hook to terminate the service before the party at telephone A replaces the receiver on the switch-hook thereat. The energizing circuit for relay 440 will be opened and it will deactivate, followed by its dependent relay 444 in sequence. Also, the lower series winding of relay 619 will de-energize, but the said relay will not deactivate and cause the restoration of connector L, due to the fact that a circuit can be traced from ground on upper armature of relay 444 through off-normal spring set RO4' (the off-normal spring set RO4' being adjusted to operate only when main element J has its wipers set on the first set of bank contact of the normal level thereof) conductor 485, armature 357, conductor 358, bank contact 624, wiper 615 to the auxiliary upper, holding winding of relay 619, thus retaining the latter relay actuated, and, therefore, preventing the restoration of connector L and the unseizing of line-switch M. At the time that relays 440 and 444 deactivate, conductor 472 is grounded for a brief period, as hereinbefore described. This ground is extended to the upper winding of relay 575, causing it to actuate and lock its lower winding through armature 576, conductor 577 to conductor 485 grounded at armature 496. A circuit can now be traced from grounded conductor 485, conductor 577, armature 578 to the winding of interruptor IR5, the said interruptor IR5 raising its plunger-arm slowly so that at a predetermined time it will link contacts 579 and 580, closing a ground path to conductor 581, conductor 547, off-normal spring 457 to the released magnet Re4, the release magnet operating to restore the shaft of the main element J to normal.

In this connection attention is directed to the fact that if the shaft of the auxiliary element K is at normal, and relay 440 of the main element J has been actuated and

is thereafter caused to be deactivated for a prolonged period, as by the party at a telephone connected through the main element J replacing the receiver thereat on the switch-hook, a ground impulse will be applied from armature 443, armature 458, conductor 459, winding of relay 502, winding of vertical magnet V5, sideswitch wiper 503 to grounded battery, the vertical magnet operating to step the shaft of auxiliary element K one step 70 so its wipers are in alignment with the first level of bank contacts thereof. However, upon the retracting of the grounded armature 445, a circuit can be traced from said armature, armature 471, conductor 472, armature 546, conductor 550, off-normal spring 551 to release magnet Re5, the release magnet operating to restore the shaft of the auxiliary element K to normal. In the same 75 manner, if relay 522 has been actuated and is thereafter caused to be deactivated for a prolonged period as by a party connected through the auxiliary element K replacing the receiver thereat on the switch-hook, a ground impulse will be applied from armature 527, armature 560, conductor 561, winding of relay 413, winding of vertical magnet V4, armature 417, sideswitch wiper 418 to grounded battery, the vertical magnet 80 operating to step the shaft of the main element J one step so its wipers are in alignment with the first level of bank contacts thereof. However, upon the retraction of grounded armature 529, a circuit can be traced from said armature, armature 566, conductor 567, armature 479, conductor 456, off-normal spring 457 to release magnet Re4, the release magnet operating to restore the shaft of the main element J to normal. 85 That is to say, if conductor 469 is grounded from off-normal spring 468 while spring 545 is disengaged, if the restoration of the shaft of main element J is effected resultant to a party at a connected local telephone replacing the receiver thereat, the conductor 469 will not become ungrounded until after it becomes grounded for a brief period at off-normal spring 545. And, if conductor 469 is grounded from off-normal spring 545 while spring 468 is disengaged, if the restoration of the shaft of auxiliary element K is effected resultant to a party at a connected local telephone replacing the receiver thereat, the conductor 469 will not become ungrounded until after it becomes grounded 90 for a brief period at off-normal spring 468.

Upon the restoration to normal of the shaft of main element J, ground will be removed from conductor 469 which will unlock relay 346. This will open the trunk circuit at armature 350, which will, in turn, cause the line relay of the connector H' to deactivate and restore the latter said connector, in the well known manner, and it will also deenergize relay 403 and its dependent relay 408 in 125 130

sequence. The relay 408 has the characteristic of being slower in releasing after de-energization than the slow-releasing relay in the connector H' dependent on the line relay thereof, to insure that the ground will not be removed from conductor 432 until the connector H' has restored, or at least until one of the selectors E' or F' has restored. When ground has been removed from conductor 432, the locking circuit of relay 347 is open, and the latter relay deactuates. Armature 357, retracting, removes ground from bank contact 624, deenergizing the auxiliary holding winding of relay 619 so relay 619 de-actuates, followed by relay 608, whereupon the circuit for operating release magnet Re6 is established to restore connector L, as hereinbefore described, lineswitch M incidentally unseizing.

From the foregoing it is clear that if the party at telephone T7 replaces the receiver on the switch-hook under the stated condition, a predetermined period, which may be adjusted to suit operating conditions, must elapse before the trunk is released and the shaft of main element J restored to normal. This retarded restoring function is provided so that in the event the calling party at telephone T7 had desired to pass the call to telephone T8, for example, by manipulating the calling device thereat (T7) in accordance with the telephone number "12" of telephone T8, wherein relay 440 would be caused to de-actuate and reactuate in accordance therewith, auxiliary element K functioning in a manner as hereinbefore described, responsive thereto, it will be possible for the said calling party at telephone T7 to have effaced the call after the first digit "1" was sent by replacing the receiver on the switch-hook for an appreciable period, wherein the shaft of the auxiliary element K will be caused to be restored from ground received from armature 445 in the manner hereinbefore described. Therefore, were it not for the described retarded restoring function, involving said interrupter IR5, the main element J would restore its shaft to normal forthwith, without allowing for a reasonable period wherein the party at telephone T7 could thereafter remove the receiver from the switch-hook, thereby unlocking relay 575 at armature 496, and directively operate the auxiliary element K to set its wipers upon a desired local line, in the manner hereinbefore described.

Assuming, in view of the last foregoing, that the response of telephone T8, for example, is attained, the called party at telephone A, the calling party at telephone T7, and the transferred-to party at telephone T8 are now in talking relation. Assuming that the calling party at telephone T7 replaces the receiver on the switch-hook, causing relays 440 and 444 to deactuate in sequence, a circuit can be traced from grounded arma-

ture 445, armature 471, conductor 472, armature 546, conductor 547, off-normal spring 457 to release magnet Re4, the release magnet operating to restore the shaft of main element J to normal. Off-normal contact set RO4' will thus restore and open the traced circuit to the holding winding of relay 619, the connector L thereupon restoring to normal, and lineswitch M unseizing, in the manner hereinbefore described. The called party at telephone A and the party at telephone T8 are now in talking relation, it being noted that ground has been maintained on conductor 469 by reason of the shaft of auxiliary element K stepping off-normal before the shaft of main element J is restored to normal. It will be noted in this connection that ground is maintained on bank contact 625 from armature 327, so that the trunk cannot be intruded upon by a connector of the group containing connector L. It will also be noted, in this connection, that when a call is initiated at the main exchange, as has been described, conductor 432 becomes grounded forthwith, and this ground is communicated through armature 348, armature 355 to the winding of relay 356, causing its armature 325 to be applied to its ground working contact, and thereby applies ground potential to bank contact 625 to guard the trunk against intrusion, a hunting connector such as L, therefore, passing over the bank contacts of the corresponding trunk and tests the successive trunk.

Assume that the party at telephone T8 desires to pass the connection to telephone T8', for example, the telephone number of which is "13". The calling device at telephone T8 will be manipulated in accordance with digits "1-3", whereupon the main element J will be caused to operate and set its wipers 701 to 704 upon bank contacts 765 to 768, and seize and ring upon the line conductors 769 and 770 leading to the said telephone T8', in the manner as hereinbefore described, it being clear that after the first passing operation, under the condition of the call having been initiated at the private automatic exchange, the subsequent passing operations and the functioning of the main element J and the auxiliary element K will be as in the described instances wherein the call was initiated at the main exchange, it being borne in mind that at the time the shaft of main element J rotated off-normal on its normal level, the rotary off-normal set RO4 operated and caused relay 421 to actuate and lock, as hereinbefore described, so that after the shaft of main element J restored responsive to the party at telephone T7 replacing the receiver on the switch-hook, the shaft of main element J was capacitated to be thereafter stepped vertically and rotarily directively, and that it will not now function on its normal level.

Assume that while the connection between the called party at telephone A and the party at telephone T8' ensued, the called party at telephone A wished to terminate the service, the party at telephone T8' still maintaining the receiver off the switch-hook. Upon replacing the receiver on the switch-hook at telephone A, the current projected over the trunk in the direction of the automatic exchange will be reversed back to the normal direction as when the trunk was primarily seized by connector L. This will mean that instead of the windings of relay 403 energizing cumulatively with the line relay windings of the connector H', the battery windings will be opposed, and there will be no current in the ground windings, and, therefore, the said relays will deactivate. Under this condition the connector H' will operate, in the well known manner, in restoring to normal, followed by selectors F' and E', and the armature 425 of relay 408 will retract to restore the shaft of the main element J to normal, in the manner as hereinbefore described.

In this connection it will be borne in mind that armature 338 is attracted due to the relay 353 being locked to conductor 628. Therefore, when relays 346 and 347 deactivate consequent to armature 424 retracting and the ground being removed from conductor 469 due to the fact that the shafts of both main element J and auxiliary element K are at normal, the connector L, although it is still connected with the trunk through bank contacts 624 to 627, has no operative relation to the trunk due to the fact that the path first traced from conductor 629 to conductor 84' is open at armature 338. Under this condition there will be no energizing circuit for the lower winding of relay 619, nor will there be an energizing circuit for the line relay of line switch C'. Relay 619 will, therefore, deactivate, followed by its dependent relay 608, whereupon the traced energizing circuit of the release magnet Re6 will be closed, restoring connector L and unseizing lineswitch M, in the manner as hereinbefore described. Ground being incidentally removed from conductor 628, the relay 353 will deactivate, after which a new call may be initiated over the trunk from the private automatic exchange, in the manner as hereinbefore described. Immediately after the unseizing of lineswitch M it will re-seize connector L, due to the fact that the party at telephone T7 has the receiver off the switch-hook thereat. Under this condition, the party at telephone T7 can forthwith directly operate connector L or replace the receiver on the switch-hook and restore actuated relays of connector L and lineswitch M to normal.

In this connection it will be manifest that since the lineswitch C' is not plunged-in, al-

though connector L may not yet have restored due to the slow-releasing characteristics of relays 619 and 608 thereof, the trunk to the private automatic exchange is unguarded at the main exchange, and is, therefore, seizable thereat, and in the event of such seizure, relay 403 will actuate and main element J will function unaffected by the unrestored condition of connector L. It will be manifest that if the trunk is seized at the main exchange and before connector L restores and removes ground from conductor 628, relay 328 will be actuated because of its energizing circuit being closed to conductor 628 by way of armature 327. Therefore, armature 308 will be attracted, and were it not for ground being applied to conductor 309 from grounded armature 360 on locked relay 353, the first set of bank contacts 705 to 708 would be unguarded, and main element J would seize them in lieu of passing over and seizing the set 709 to 712 leading to the attendant's telephone T7'.

In this connection attention is directed to the fact that when connector L seized bank contacts 624 to 627, and the call was thereafter extended to the called telephone A in the main exchange and the called party responded, causing relay 347 to actuate, the reversing relay 447 was incapacitated by reason of armature 312 of relay 347 being attracted. That is to say, relay 447 only functions on calls incoming to the private automatic exchange.

Attention is directed to the fact that while but three sets of bank contacts are shown in each level accessible to the elements J and K and connector L, a larger number of sets may be employed. As applied to the normal level accessible to element J it provides for a larger number of alternative attendant's lines. Also, the lines leading from the banks accessible to J and K may be isolated, or be in groups. The auxiliary element K, while not group-selecting, may be readily made so by those skilled in the art, by applying the circuit devices thereto as are employed in main element J, with relation to the private magnet, the interrupter relay and the auxiliary private wiper and circuits associated.

Attention is also directed to the fact that when a call is being passed, relay 470 or 565, as the case may be, of the element connected to the telephone passing, will be actuated, which will serve to disconnect the talking party so the directive impulses will not be heard by the party in the main exchange (at telephone A, for example) holding the trunk.

Assume that the sheets are assembled in accordance with Fig. 12, the trunk from the private automatic exchange thus terminates in a springjack TJ in the manual exchange in lieu of a lineswitch C' in the automatic exchange, as was hereinbefore assumed. It

will now be also assumed that Fig. 11 is introduced into the main element J in Fig. 4 as indicated by the section lines, *a*, *b*, and *c*, so that relay 447' will displace relay 447, and that conductor 313 leading from the winding of relay 447 is disassociated and the conductor leading from the winding of relay 447' attaches to conductor 446.

It will be observed that conductor 84' is related to the battery winding of line relay 150, by way of armature 151 on line cut-off relay 152, and that conductor 83' is related to the ground winding of the relay 150 by way of armature 153 on the relay 152. In view of the foregoing description it is clear that the relay 150 will not energize under this condition. However if a call is initiated at telephone T7 in the private automatic exchange, and the trunk seized by connector L, in the manner as hereinbefore described, the relay 150 will be operatively energized in the manner that the line relay of the lineswitch C' was operatively energized when the trunk was seized by connector L in foregoing descriptions. Upon the relay 150 actuating, armature 155 will apply its ground to energize calling lamp 156. Due to relay 328 actuating incidental to the connector L seizing the trunk, the main element J will be caused to function on its normal level and seize the first set of bank contacts 705 to 708, in the manner before described, preparatory to completing the connection from the calling station T7 to the trunk via the main element J, in lieu of being directly connected to the trunk, upon the actuation of relay 334, which will occur upon a response being attained from the operator at the main exchange, as will appear presently, and in view of foregoing descriptions.

Upon the operator at the main exchange observing the glowing of lamp 156, plug PA will be inserted into the springjack TJ. A circuit can be traced from the grounded winding of relay 152, sleeve of plug PA, resistance 157, to the free terminal of supervisory lamp 158, the said lamp glowing and the relay 152 actuating to disassociate the line relay 150 and extinguish the lamp 156. It will now appear that ground is applied through the upper winding of the repeating coil 159 and tip conductor of plug PA to conductor 84', and that battery is applied through the lower winding of said repeating coil through shunted supervisory relay 160, ring of plug PA to conductor 83'. Current is thus maintained through the telephone T7 but in the reversed direction than primarily established involving the windings of relay 150, and due to the reversal of current projected over the trunk incidental to the insertion of the switching plug PA into springjack TJ upon the operator responding, the relay 334 will operatively energize and cause relays 346, 347, and 353 to actuate, in the

manner as hereinbefore described, when the current was reversed over the trunk in the out-going call from telephone T7 to telephone A, incidental to the party at telephone A responding. The main exchange being manual, the party at telephone T7 will not manipulate the calling device thereat further than the sending of digit "0" to attain connection with the trunk, it being the only directive calling device operative in making such a call. However, it will be manifest that since the circuits and equipments at the private automatic exchange are now in the same state as when the party at telephone A responded in the referred-to call, (having in mind that relay 447' does not affect the operation so far as the private automatic exchange is concerned) the party at telephone T7 may forthwith manipulate the calling device thereat effective to passing the call through the auxiliary element K to telephone T8', for example. The operator at the main exchange may extend the connection to any called telephone, T10 for example, through the agency of companion calling plug PC.

At the time plug PA was inserted into springjack TJ relay 160 was energized, attracting its armature 161 to apply grounded battery through resistance 163 to the free terminal of lamp 158, causing the said lamp to extinguish, in the well known manner. If the party at telephone T7, in lieu of passing the connection to telephone T8, replaces the receiver on the switch-hook thereat, the interrupter IR5 will operate, in the manner as hereinbefore described, and in its predetermined period, cause the restoration of the shaft of the main element J to normal, in the manner as hereinbefore described, whereupon relays 346 and 347 will deactivate and open the traced circuit including the winding of supervisory relay 160 at the main exchange at armature 350, and in view of the fact that the upper winding of relay 619 became deenergized consequent to the restoration of the shaft of the main element J, and the further fact that relay 353 is locked, the lower winding of relay 619 is now deenergized and the relays 619 and 608 will deactivate in sequence consistent with their releasing periods, causing the connector L to be restored and the lineswitch M to be unseized, in the manner as hereinbefore described.

At the time the main element J rotated off-normal consequent to the actuation of relay 328 incidental to the connector L seizing the trunk leading to the main exchange, ground was applied through off-normal spring 468 to conductor 469; this conductor being maintained grounded until the shafts of both main element J and auxiliary element K have been restored to normal, as has been set forth hereinbefore. Then, upon the operator at the main exchange inserting the plug PA into springjack TJ, causing relays 334, 346, 347,

and 353 in Fig. 3 to actuate, followed by the actuation of relays 436, 440, and 444 in the main element J, due to relay 436 becoming energized in the path including the receiver of the calling telephone T7, in the manner as hereinbefore described, conductor 446 will be grounded through armature 445, and, therefore, the relay 447' will be actuated therefrom and locked through its armature 466' to conductor 469. The actuation of relay 447' will short-circuit resistance r_4 at armature 461', thus maintaining relay 160 in the switching cord-pair Q fully energized, it being understood that the relay 160 is marginally adjusted so that its armature 161 will retract if resistance r_4 is included in its energizing path. The calling party at telephone T7 is now related to the trunk leading to the switching cord-pair Q as it was when the call was described as from telephone T7 to called telephone A in the main automatic exchange, (with particular reference to the direction of current flow over the trunk conductors), and the party at telephone A had responded.

It will be clear that since the private automatic exchange main and auxiliary elements, J and K, are disposed as they were wherein a connection was described as extended from telephone T7 to telephone A in the main automatic exchange, the party at telephone T7 can pass the connection to telephone T8 and the party at telephone T8 can pass the connection to telephone T8', etc., as hereinbefore described.

Going back to the condition of the circuits at the time the party at telephone T7 replaced the receiver on the switch-hook thereat, in the last exampled call, relays 440 and 444 will deactivate, causing the stated operation of interrupter IR5 and the restoration of the shaft of the main element J to normal, which condition causes the ground to be removed from conductor 469, unlocking relay 447' and thereby introducing the resistance r_4 into the energizing circuit of relay 160 in the cord-pair Q, the armature 161 retracting to cause the lamp 158 to glow as a clearing signal, after which the plug PA may be withdrawn. Under the condition described last in which the plug PA is in springjack TJ, the upper winding of relay 403 is energized through the ground winding of the repeating coil 159 in the cord-pair, and the lower winding of relay 403 is energized through the battery winding of the said repeating coil. It will be understood in this connection, that the relay 440 will derive enough current through the resistance r_4 under the condition described to operatively energize and maintain it, though relay 160 in the cord-pair will deactivate. Under this condition, relays 403 and 408 do not deactivate, and, therefore, relay 347 does not unlock, which forestalls a false operation of the main ele-

ment J on its normal level, and the attracted armature 327 will apply a busy ground to conductor 628 to guard the trunk against being seized for an outgoing connection by any of the connectors of the group containing L, until the operator withdraws the plug PA. The inserted plug PA at the main exchange thus maintains the trunk guarded against intrusion at the private automatic exchange end until the said plug is withdrawn, so confusion by way of a new call being completed to the trunk before a previous connection is completely effaced, is prevented.

Assume that it was desired to complete a connection to telephone T10 after the operator answered the glowing of lamp 156. Plug PC would be inserted into springjack LJ and ringing key RK depressed to apply signaling current from the generator G10, effective to the signal device at telephone T10. Then, upon the party at telephone T10 responding by removing the receiver from the switchhook thereat, a talking path will exist between telephone T7 and telephone T10.

Assume that the operator at the main exchange withdraws the plug PA while the party at telephone T7 is still connected to the trunk through main element J. The windings of relays 150 and 403 will be as normally related, so the relay 403 will deactivate and thereby cause the restoration of the shaft of main element J to normal. However, since relay 353 will remain locked until the connector L restores, because relay 619 is now deenergized and will deactivate, the trunk line relay 150 will not actuate. Upon relay 353 deactivating after the connector L restores the trunk equipment at both ends thereof is at normal.

If the operator at the main exchange reinserts the plug PA into springjack TJ thereafter, though the connector L has not had time to restore, the said call will cause the main element J to function normally and seize bank contacts 709 to 712, unaffected by the said seized condition of connector L.

Had the connection been passed and telephone T8 was connected through the auxiliary element K, in lieu of telephone T7 through the main element J, if the party at telephone T8 replaced the receiver on the switch-hook, auxiliary element K would restore forthwith, in the manner as hereinbefore described, causing the relay 447' to deactivate, and the lamp 158 to glow as a clearing signal to the main exchange operator. If the operator at the main exchange withdraws the plug PA before the party at telephone T8 replaces the receiver, the auxiliary element K will be restored because of the deactivation of relay 408, as described, whereupon the equipments of the trunk are at normal.

The cord-pair Q has a calling device key CK for introducing the calling device CD into the trunk, so that after the plug PA is

inserted into springjack TJ and the main element J functions on its normal level and seizes the line extending to telephone T, the calling device CD may be manipulated 5 (the key CK having been operated either before or after inserting the plug) and auxiliary element K directively operated and the relay 436 locked to cut off the source G4, in the manner as before described, wherein the 10 party at the calling telephone A in the main exchange directively operated auxiliary element K and relay 436 under corresponding conditions.

It is manifest that various other changes 15 and modifications (either as an amplification or as a curtailment) may be made to the system chosen to elucidate the functions and operations of the present invention, as hereinbefore described, in adapting the invention 20 to the manifold requirements of commercial operation, without departing from the scope thereof, in view of the subjoined claims.

I claim:—

1. In a telephone system, telephone lines, 25 automatic switches, means under control of a party on a calling one of said lines for operating a series of said switches in order to extend a connection to a first called one of said lines, means under control of the party 30 on the said called line for directively extending a connection to a second called line from a point intermediate of the calling and the called lines, whereby the calling line, the first called line and the second called line are in 35 telephonic relation, and means operated upon a response on the second called line, dependent upon the first called line being connected, for applying a specific tone audible to the party on the second called line.

40 2. In a telephone system, telephone lines, automatic switches, means under control of a party on a calling one of said lines for operating a series of said switches in order to extend a connection to a first called one of said lines, means under control of the party 45 on the said called line for directively extending a connection to a second called line from a point intermediate of the calling and called lines, whereby the calling line, the first called 50 line and the second called line are in telephonic relation, and means operated upon a response on the second called line, dependent upon the first called line being connected for briefly applying a specific tone audible to 55 the party on the second called line.

3. In a telephone system, telephone lines, 60 automatic switches, means under control of a party on a calling one of said lines for operating a series of said switches in order to extend a connection to a first called one of said lines, means under control of the party on the said called line for directively extending a connection to a second called line from a point intermediate of the calling and the 65 called lines, whereby the calling line, the

first called line and the second called line are in telephonic relation, means operated upon a response on the second called line, dependent upon the first called line being connected, for applying a specific tone audible to the party on the second called line, and means for again applying a specific tone audible to the party on the second called line consequent to the first called party disconnecting. 70

4. In a telephone system, telephone lines, 75 automatic switches, means under control of a party on a calling one of said lines for operating a series of said switches in order to extend a connection to a first called one of said lines, means under control of the party on the said called line for directively extending a connection to a second called line from a point intermediate of the calling and the called lines, whereby the calling line, the first called line and the second called line are in 80 telephonic relation, means operated upon a response on the second called line, dependent upon the first called line being connected for applying a specific tone audible to the party on the second called line, and means for applying a specific tone audible to the party on the first called line consequent to the second called party disconnecting. 85

5. In a telephone system, telephone lines, 90 automatic switches, means under the control of a party on a calling one of said lines for operating a series of said switches in order to extend a connection to a first called one of said lines, means under control of the party on the said called line for reversing the direction of current projected back over the calling line, means controlled from the party on the said called line for directively extending a connection to a second called line from a point intermediate of the calling and the called lines, and means for the party on the first called line disconnecting while maintaining the connection from the calling line to the second called line and for maintaining the said reversed direction of current regardless of the responded or non-responded condition of the second called line. 95

6. In a telephone system, telephone lines, 100 automatic switches, means under the control of a party on a calling one of said lines for operating a series of said switches in order to extend a connection to a first called one of said lines, means under control of the party on the said called line for reversing the direction of current projected back over the calling line, means controlled from the party on the said called line for directively extending a connection to a second called line from a point intermediate of the calling and the called lines, means for the party on the first called line disconnecting while maintaining the connection from the calling line to the second called line and for maintaining the said reversed direction of current regardless of the responded or non-responded condition 105 110 115 120 125 130

5 of the second called line, and means for reversing the current direction projected back over the calling line to the initial direction consequent to the party on the second called line responding and subsequently disconnecting.

10 7. In a telephone system, telephone lines, automatic switches, means under the control of a party on a calling one of said lines for operating a series of said switches in order to extend a connection to a first called one of said lines, means under control of the party on the said called line for changing the character of current projected back over the 15 calling line, means controlled from the party on the said called line for directly extending a connection to a second called line from a point intermediate of the calling and the called lines, and means for the party on the 20 first called line disconnecting while maintaining the connection from the calling line to the second called line and for maintaining the said changed character of current regardless of the responded or non-responded condition of the second called line.

25 8. In a telephone system, telephone lines, automatic switches, means under the control of a party on a calling one of said lines for operating a series of said switches in order to extend a connection to a first called one of said lines, means under control of the party on the said called line for changing the character of current projected back over the calling line, means controlled from the party on the 30 said called line for directly extending a connection to a second called line from a point intermediate of the calling and the called lines, means for the party on the first called line disconnecting while maintaining the connection from the calling line to the second called line and for maintaining the said changed character of current regardless of the responded or non-responded condition of the second called line, and means for restoring the character of current projected back over the calling line to the initial character consequent to the party on the second called line responding and subsequently disconnecting.

35 50 9. In a telephone system, telephone lines, automatic switches including a connector, means under control of a party on a calling one of said lines for operating a series of said switches in order to extend a connection to the connector, means in the said connector for automatically initiating its functioning in a first direction whereby it will automatically connect with a called line, means on the called line for directly extending a 40 connection to a second called line from a point intermediate of the calling and the called lines, whereby the calling line, the first called line, and the second called line are in telephonic relation, means for disconnecting the first called line and restoring the said

45 connector, and means controlled from the second called line for directly extending a connection to a third called line from a point intermediate of the calling line and the second called line through the agency of the 50 said connector functioning initially in a different direction from the said first direction.

55 10. In a telephone system, telephone lines, automatic switches including a connector, means under control of a party on a calling one of said lines for operating a series of said switches in order to extend a connection to the connector, means in said connector for automatically initiating its functioning in a first direction whereby it will automatically select and connect with a disengaged one of a called group of lines, means on the line called for directly extending a connection to a second called line from a point intermediate of the calling and called lines, whereby the calling line, the line first called and the second called line are in telephonic relation, means for disconnecting the first called line and restoring the said connector, and means controlled from the second called line for directly extending a connection to a third called line from a point intermediate of the calling line and the second called line through the agency of the said connector functioning initially in a different direction from the said first direction.

60 11. In a telephone system, telephone lines, automatic switches including a first and a second connector element, means under control of a party on a calling one of said lines for operating a series of said switches in order to extend a connection to the connector, means in said first connector element for automatically initiating its functioning whereby it will automatically connect with a called line, means associated with the said first connector element operative at a predetermined period after the connection is completed from the said first connector element to the called line for applying signalling current to the called line, means under control of the party on the calling line for directly operating the said second connector element whereby a second called line can be linked to the calling line, and means whereby upon the first directive operation effective to the said second connector element the said first connector element connected with the first said called line will be disabled against applying signalling current to the first said called line.

65 12. In a telephone system, telephone lines, automatic switches, means under control of a party on a calling one of said lines for operating a series of said switches in order to extend a connection to a first said switch, means in said first switch for automatically initiating its functioning whereby it will automatically connect with a called line, means associated with the said first switch operative at a predetermined period after the connec-

tion is completed to the called line for applying signaling current to the called line, means under control of the party on the calling line for directively operating a second said switch whereby a second called line can be linked to the calling line, and means whereby upon the first directive operation effective to the second switch the switch connected with the first said called line will be disabled against applying signaling current to the first said called line.

13. In a telephone system, telephone lines, automatic switches, means under control of a party on a calling one of said lines for operating a series of said switches in order to extend a connection to a first said switch, means in said switch for automatically initiating its functioning whereby it will automatically connect with a called line, means associated with the switch operative at a predetermined period after the connection is completed to the called line for applying signaling current to the called line, means under control of the party on the calling line for directly operating a second said switch whereby a second called line can be linked to the calling line, means whereby upon the first directive operation effective to the said second switch involved in the connection to the second called line the switch connected with the first said called line will be disabled against applying signaling current to the first said called line, and means controlled consequent to a response being made on the said second called line for disconnecting the first said called line.

14. In a telephone system, telephone lines, automatic switches, means under control of a party on a calling one of said lines for operating a series of said switches in order to extend a connection to a said switch, means in said switch for automatically initiating its functioning whereby it will automatically connect with a called line, means associated with the switch operative at a predetermined period after the connection is completed to the called line for applying signaling current to the called line, means under control of the party on the calling line for directly operating a second switch whereby a second said called line can be linked to the calling line, means whereby upon the first directive operation effective to the second switch the switch connected with the first said called line will be disabled against applying signaling current to the first said called line, means controlled consequent to a response being made on the said second called line for disconnecting the first said called line, and means controlled on the said second called line for directly controlling the switch which connected to the first said called line whereby the last said switch will be caused to connect with and forthwith apply signaling current to a third called line.

15. In a connector switch, means for causing it to automatically initiate its selective operation on a normal level thereof upon it being seized by a cooperating switch, means in the connector for seizing the first unguarded line encountered in said normal level, means for causing the connector to be released from the seized line, and means operative dependent upon the said operation of the connector to capacitate it to thereafter function directly without first disengaging it.

16. In a connector switch, means for causing it to automatically initiate its selective operation upon its being seized by a cooperating switch, means in the connector for seizing the first unguarded line encountered, means for causing the connector to be released from the seized line, and means for capacitating the connector to forthwith thereafter operate directly without first disengaging it.

17. In a telephone system, a trunk line terminating in a connector, means for seizing the trunk line, means in the connector operative consequent to the seizure of the trunk line for causing the connector to forthwith automatically function as a selector and seize the first unguarded subscriber's telephone line, means on the said telephone line seized for directly disconnecting the connector from the said telephone line, and means for adapting the connector to first thereafter function responsive to directive control.

18. In a telephone system, a trunk line terminating in an automatic switch, means for seizing the said switch from the remote end of the trunk line, means in the said switch operative consequent to the said seizure to cause the said switch to rotate from its normal position as a selector and seize and signal upon the first unguarded line, means on the line seized to cause the said switch to disconnect from the seized line, and means for capacitating the said switch to be first thereafter operated by directive control.

19. In a telephone system, a trunk line terminating in an automatic switch, means for seizing the said switch from the remote end of the trunk line, means in the said switch operative consequent to the said seizure to cause the said switch to rotate from its normal position as a selector and seize the first unguarded line, means on the line seized for introducing a second called line into the connection, means on the said second line for disconnecting the said switch from the said first unguarded line seized, and means for capacitating the said switch to be first thereafter operated by directive control.

20. In a telephone system, a trunk line terminating in an automatic switch, means for seizing the said switch from the remote end of the trunk line, means in the said switch

operative consequent to the said seizure to cause the said switch to rotate from its normal position as a selector and seize the first unguarded line, means on the line seized for 5 introducing a second called line into the connection, means on the said second line for disconnecting the said switch from said first unguarded line seized, and means for 10 capacitating the said switch to be first thereafter operated vertically by directive control.

21. In a telephone system, a trunk line terminating in an automatic switch, means for seizing the said switch from the remote end 15 of the trunk line, means in the said switch operative consequent to the said seizure to cause the said switch to rotate from its normal position as a selector and seize the first unguarded line, means on the line seized for 20 introducing a second called line into the connection, means on the said second line for disconnecting the said switch from said first unguarded line seized, and means for 25 capacitating the said switch to be first thereafter operated vertically by directive control and thence horizontally by directive control.

22. In a telephone system, telephone lines, a trunk line, a tone source, the trunk line 30 terminating in automatic switch mechanism, means for operating the switch mechanism to connect the trunk line with a first one of said lines, means for introducing a second line into the connection whereby a Y connection 35 will ensue between the trunk line and other said lines, means whereby either the first or the second said lines can be disconnected from the connection leaving a two-line connection, and means whereby the tone 40 source will be automatically connected audible to the connected first or second line consequent to the disconnection of the alternative first or second line to indicate the condition.

45 23. In a telephone system, three lines interlinked in a Y connection, a tone source, means on a said line for controlling its disconnection from the other two lines, and automatic means effective consequent to a said 50 disconnection for applying the tone source audible on one of the lines remaining in connection indicative that the said disconnection has occurred.

24. In a telephone system a trunk line, 55 a selective switch mechanism connected to the near end of the trunk line controlled from the remote end thereof, a selector for completing a connection from a calling line to the near end of the trunk line, and means 60 for initiating the operation of the switch mechanism after the near end of the trunk line is seized by the selector to cause the switch mechanism to seize the selector and disassociate the trunk line from its seizure, 65 whereby an alternative path has been com-

pleted from the selector to the near end of the trunk line involving the said switch mechanism interposed therein.

25. In a telephone system a trunk line, a 70 selective switch mechanism connected to the near end of the trunk line controlled from the remote end thereof, a selector for completing a connection from a calling line to the near end of the trunk line, means for initiating the operation of the switch mechanism after the near end of the trunk line is seized by the selector to cause the switch mechanism to seize the selector and disassociate the trunk line from its seizure, 75 whereby an alternative path has been completed from the selector to the near end of the trunk line involving the said switch mechanism interposed therein, and means for then directly controlling the switch mechanism from the calling line in lieu of controlling it from the remote end of the trunk line to effect a connection from the trunk line to a called line.

26. In a telephone system a trunk line, a 80 selective switch mechanism connected to the near end of the trunk line controlled from the remote end thereof, a selector for completing a connection from a calling line to the near end of the trunk line, means for initiating the operation of the switch mechanism after 85 the near end of the trunk line is seized by the selector to cause the switch mechanism to seize the selector and disassociate the trunk line from its seizure, whereby an alternative path has been completed from the selector to the near end of the trunk line involving the said switch mechanism interposed therein, means for then directly controlling the switch mechanism from the calling line 90 in lieu of controlling it from the remote end of the trunk line to effect a connection from the trunk line to a called line, and means whereby the calling line, the trunk line and the called line are thereby in telephonic relation.

27. In a telephone system, a trunk line, a selective switch mechanism connected to the near end of the trunk line subject to directive control of means from the remote end of the trunk line over the trunk line, 100 a selector for completing a connection from a calling line to the near end of the trunk line, and means for initiating the operation of the switch mechanism after the near end of the trunk line is seized by the selector to cause the switch mechanism to seize the selector and disassociate the trunk line from the seizure, whereby an alternate path has been completed from the selector to the near end of the trunk line involving the said 105 switch mechanism interposed therein.

28. In a telephone system, a trunk line, a selective switch mechanism connected to the near end of the trunk line subject to directive control of means from the remote end 110

- of the trunk line over the trunk line, a switch for completing a connection from a calling line to the near end of the trunk line, means for initiating the operation of the 5 switch mechanism after the near end of the trunk line is seized by the switch to cause the switch mechanism to seize the selector and disassociate the trunk line from the seizure, whereby an alternative path has been completed from the switch to the near end 10 of the trunk line involving the said switch mechanism interposed therein, and means for directly controlling the switch mechanism from the calling line in lieu of controlling it from the remote end of the trunk line to effect a connection from the trunk line to a called line. 15
29. In a telephone system, a trunk line, a first and a second called line, a pair of connectors consisting of a first and a second element terminating the near end of the trunk line, a switch, means for seizing the trunk line at the remote end thereof and thereby causing the said first element to extend the 20 connection to the first called line, means on the first called line for directly controlling the said second element and thereby causing the said second element to extend the connection to the second called line, a third line 25 and means thereon for initiating a new call and for directly operating the switch to effect a connection from the third line to the near end of the trunk line, means operative after seizing the trunk line by the said switch to cause the said first element to effect a connection with the said third line through the said switch and disassociate the said switch from the near end of the trunk and re-connect it to the near end of the trunk over 30 a path wherein the first element is interposed, and means for then directly operating the said second element from the said third line whereby the said first called line can be introduced into the connection so a talking relation 35 exists between the said third line, the trunk line and the said first line. 40
30. In a telephone system, a two-way trunk line, a first and a second called line, a pair of connectors consisting of a first and a second element terminating the near end of the trunk line, means for seizing the trunk line at the remote end thereof and thereby causing the said first element to extend the connection to the first line, means on the said 45 first line for directly controlling the said second element and thereby causing the said second element to extend the connection to the second line, means on the said first line for initiating a new call and for directly 50 operating the switch to effect a connection therefrom to the near end of the trunk line, means operative after seizing the trunk line by the said switch to cause the said first element to effect a connection with the said first line through the said switch and disassociate 55 the said switch from the near end of the trunk and re-connect it to the near end of the trunk over a path wherein the said first element is interposed, and means for then directly operating the said second element from the said first line whereby the said second line can be introduced into the connection so a talking relation exists between the said first line, the said second line and the exchange line. 60
31. In a telephone system, a two-way trunk line, a first and a second called line, a directive switch, a switch, an exchange line, a pair of connectors consisting of a first and a second element terminating the near end of the trunk line, the remote end of which is connected to the directive switch, means for seizing the trunk line at the remote end thereof and thereby causing the said first element to automatically extend the connection to the first line, means on the said first line for directly controlling the said second element and thereby causing the said second element to extend the connection to the second line, means on the said first line for initiating a new call and for directly operating the said switch to effect a connection therefrom to the near end of the trunk line and for directly extending the connection through the said directive switch at the remote end of the trunk line to the exchange line, means operative after seizing the trunk line by the said switch to cause the said first element to effect a connection with the said first line through the said switch and disassociate the said switch from the near end of the trunk and re-connect it to the near end of the trunk over a path wherein the said first element is interposed, and means for then directly operating the said second element from the said first line whereby the said second line can be introduced into the connection so a talking relation exists between the said first line, the said second line and the exchange line. 65

- 5 mated end of the trunk line to the exchange line, means operative after seizing the trunk line by the said switch to cause the said first element to effect a connection with the said first line through the said switch and dis-
 10 associate the said switch from the near end of the trunk and re-connect it to the near end of the trunk over a path wherein the said first element is interposed, means for then direc-
 15 tively operating the said second element from the said first line whereby the said second line can be introduced into the connection so a talking relation will exist between the said first line, the said second line and the exchange line, and means for effacing the operated state of the equipment at the near end and the far end of the trunk under control of the said exchange line and for effacing the operated state of the equipment at the far
 20 end and the near end of the trunk under control of the said first and said second lines.
33. In a telephone system, a two-way trunk line, a first and a second called line, a directive switch, a switch, an exchange line, a pair of connectors consisting of a first and a second element terminating the near end of the trunk line the remote end of which is connected to the directive switch, means for seizing the trunk line at the remote end thereof and thereby causing the said first element to automatically extend the connection to the first line, means on the said first line for directly controlling the said second element and thereby causing the said second element to extend the connection to the second line, means on the said first line for initiating a new call and for directly operating the said switch to effect a connection therefrom to the near end of the trunk line and for directly extending the connection through the said directive switch at the remote end of the trunk line to the exchange line, means operative after seizing the trunk line by the said switch to cause the said first element to effect a connection with the said first line through the said switch and disassociate the said switch from the near end of the trunk and re-connect it to the near end of the trunk over a path wherein the said first element is interposed, means for then directly operating the said second element from the said first line whereby the said second line can be introduced into the connection so a talking relation will exist between the said first line, the said second line and the trunk line, means whereby either the said first or the said second line may be disconnected from the latter said established connection, leaving the other line and the trunk line of the connection in talking relation, and means controlled from the connected line at either end of the trunk line for effacing the connection.
35. In a telephone system, a two-way trunk line, a first and a second called line, a directive switch, a switch, an exchange line, a third line, a pair of connectors consisting of a first and a second element terminating the near end of the trunk line the remote end of which is connected to the directive switch, means for seizing the trunk line at the remote end thereof and thereby causing the said first element to effect a connection with the said first line through the said switch and disassociate the said switch from the near end of the trunk and re-connect it to the near end of the trunk over a path wherein the said first element is interposed, means for then directly operating the said second element from the said first line whereby the said second line can be introduced into the connection so a talking relation will exist between the said first line, the said second line and the trunk line, and control means whereby either the said first or the said second line may be disconnected from the latter said established connection, leaving the other line and the trunk line of the connection in talking relation.
34. In a telephone system, a two-way trunk line, a first and a second called line, a directive switch, a switch, an exchange line, a pair of connectors consisting of a first and a second element terminating the near end of the trunk line the remote end of which is connected to the directive switch, means for seizing the trunk line by the said switch to cause the said first element to effect a connection with the said first line through the said switch and disassociate the said switch from the near end of the trunk and re-connect it to the near end of the trunk over a path wherein the said first element is interposed, means for then directly operating the said second element from the said first line whereby the said second line can be introduced into the connection so a talking relation will exist between the said first line, the said second line and the trunk line, and control means whereby either the said first or the said second line may be disconnected from the latter said established connection, leaving the other line and the trunk line of the connection in talking relation.

tively operating the said second element from the said first line whereby the said second line can be introduced into the connection so a talking relation will exist between the said 5 first line, the said second line and the trunk line, means whereby either the said first or the said second line may be disconnected from the latter said established connection leaving the other line and the trunk line of 10 the connection in talking relation, and means controlled from the line remaining connected with one of the said elements for then operating the other said element to introduce the third line into the connection with the remaining 15 said line and the trunk line.

36. In a telephone system, a trunk line, a first and a second line, a switch, an exchange line, a pair of connectors consisting of a first and a second element terminating the near 20 end of the trunk line, a directive switch connected to the remote end of said trunk, means on the first line for initiating a call and for directly operating the switch to effect a connection therefrom to the near end of the 25 trunk line and for directly extending the connection through the said directive switch at the remote end of the trunk line to the exchange line, means operative after seizing the trunk line by the said switch to cause the 30 said first element to effect a connection with the said first line through the said switch and disassociate the said switch from the near end of the trunk and re-connect it to the near end of the trunk over a path wherein the said 35 first element is interposed, means for then directly operating the said second element from the said first line whereby the said second line can be introduced into the connection so a talking relation will exist between 40 the said first line the said second line and the trunk line, and means whereby either the said first or the said second line may be disconnected from the latter said established connection, leaving the other two lines of the 45 connection in talking relation.

37. In a telephone system, a trunk line, a first and a second line, a switch, an exchange line, a third line, a pair of connectors consisting of a first and a second element terminating the near end of the trunk line, a directive switch connected to the remote end of said trunk, means on the first line for initiating a call and for directly operating the switch to effect a connection therefrom to the 50 near end of the trunk line and for directly extending the connection through the said directive switch at the remote end of the trunk line to the exchange line, means operative after seizing the trunk line by the said switch 55 to cause the said first element to effect a connection with the said first line through the said switch and disassociate the said switch from the near end of the trunk and re-connect it to the near end of the trunk over a path 60 wherein the said first element is interposed,

means for then directly operating the said second element from the said first line whereby the said second line can be introduced into the connection so a talking relation will exist between the said first line the said second line and the trunk line, means whereby either the said first or the said second line may be disconnected from the latter said established connection, leaving the other two lines of the connection in talking relation, and means whereby the line remaining connected with one of the said elements can then operate the other said element to introduce the third line into the connection with the remaining said line and the trunk line.

38. In a telephone system, a trunk line, a switch, a first and a second line, two inter-linked switch elements terminating the near end of the trunk line, means on the first line for initiating a call and for directly operating the switch to complete a connection therefrom to the near end of the trunk line, means operative after seizing the said trunk line by the said switch for enabling the first line to directly control one of the said inter-linked switch elements to introduce the second line into the connection with the first line and the trunk line, means for disassociating the first line from the connection at will, and means controlled from the second line whereby the other said inter-linked switch element can be directly operated from the second line to introduce the third line into the connection with the trunk and the second line.

39. In a telephone system, three lines, a switch mechanism, a tone source, means for effecting a connection between a first and a second of said lines, means for then connecting a third one of said lines with said second line to form a Y talking connection of the three lines upon a response occurring upon the said third line, means controlled from the said first line for disconnecting it from its connection before or after the response occurs on the said third line, means automatically effective dependent upon the said first and second lines being maintained connected for causing the tone source to be applied audible to the third line consequent upon a response thereon, and means automatically effective for applying the tone source to the connected third line consequent upon the said first line disconnecting from the connection during the responded condition of the said third line.

40. In a telephone system, interlinking switch mechanism, a tone source, a plurality of lines interlinked in a star connection through the agency of the switch mechanism, means on a said line for controlling its disconnection from the other lines, and automatic means effective consequent to a said disconnection for applying the tone source audible on one of the lines remaining in con-

nection indicative that the said disconnection has occurred.

41. In a telephone system, lines, automatic switch mechanism, means under control of a party on a calling one of said lines for operating said switch mechanism in order to extend a connection to a first called one of said lines, means controlled from the said called line for reversing the direction of current projected back over the calling line, means controlled by the party on the said called line for directly extending a connection to a second called line from a point intermediate of the calling and the called lines, and means for the party on the first called line disconnecting while maintaining the connection from the calling line to the second called line for maintaining the said reversed direction of current regardless of the responded or non-responded condition of the second called line.
42. In a telephone system, a calling line, switch mechanism, a calling station, lines, means for connecting the calling station to the calling line to cause a first element of said switch mechanism to forthwith automatically operate in a single plane to extend a connection from the calling line to a first one of said lines responsive to the said connecting of the calling station, means on the said called line for directly controlling a second element of said switch mechanism in two planes to extend a connection to a second one of said lines forming a Y connection between the calling line and the said first and second ones of said lines, means for disconnecting the said first element from the said first line, and automatic means for thereafter at will directly operating an element of the mechanism into connection with a third one of said lines forming a Y connection between the calling line and the said second and third ones of said lines without terminating the call.

43. In a telephone system, a calling line, switch mechanism, a calling station, lines, means for connecting the calling stations to the called line to cause a first element of said switch mechanism to forthwith automatically extend a connection from the calling line to a first one of said lines responsive to the said connecting of the calling station, means on the said calling line for then directly controlling a second element of said switch mechanism to extend a connection to a second one of said lines forming a Y connection between the calling line and the said first and second ones of said lines, means for disconnecting the said first element from the said first line, and automatic means for thereafter at will directly operating an element of the mechanism into connection with a third one of said lines forming a Y connection between the calling line and the said second and third ones of said lines without terminating the call.

44. In a telephone system, a calling line, a

non-directive single plane switch which will alternatively function as a step-by-step directive switch in two planes, means to initiate a call to the switch, lines accessible from the switch, automatically applied means whereby the switch will be caused to forthwith automatically hunt in a single plane as a non-directive switch to connect the calling line with a said accessible line responsive to the initiation, mechanism for changing the switch from a non-directive single plane switch to a step-by-step directive switch which will operate in two planes, and automatically applied means effective consequent to its said non-directive operation for operating the said mechanism whereby the switch may thereafter function as an automatic step-by-step directive switch in two planes to alternatively connect the calling line with another of said accessible lines, the said directive functioning in two planes being dependent upon maintaining the said initiation.

45. In a telephone system, a two-conductor calling line, a non-directive single plane switch which will also function as a step-by-step directive switch in two planes, a line accessible from the switch, manually controlled means for joining the conductors of the calling line to initiate a call to cause the switch to automatically function in a single plane as a non-directive switch to connect the calling line to said accessible line, means for restoring the switch from the connected accessible line while maintaining the initiation of the call, means whereby the switch will be disabled from automatically functioning as a non-step-by-step directive switch and enabled to function as a directed switch operating in two planes consequent to its non-directive functioning, and means whereby the switch will thereafter operate in two planes under automatic directive control for again connecting the calling line to the said line before connected with dependent upon the call not being effaced.

46. In a telephone system, a two-conductor calling line, a non-directive switch which will also function as a directive switch, lines accessible from the switch, means for joining the conductors of the calling line to initiate a call to cause the switch to function as a non-directive switch to connect the calling line to a said accessible line, means controlled from the calling line for restoring the switch from the connected accessible line, means whereby the switch will be disabled from automatically functioning as a non-directive switch and enabled to function as a step-by-step directed switch consequent to the non-directive operation, and means whereby the switch will thereafter operate under step-by-step directive control from the calling line dependent upon the call not being effaced.

47. In a telephone system, a two-conductor calling line, switch mechanism, first and

- second lines accessible from a first element of said mechanism, a third line accessible from a second element of said switch mechanism, means whereby joining the said two-conductors will cause the said first element to automatically function to extend a connection from the calling line to the said first line, means on the calling line to thereafter at will directly operate the second one of said elements to extend a connection from the calling line to the said third line, automatic means for disconnecting the first one of said elements from its connection with said first line, and automatic means then directly 10 step-by-step operated at will to cause the said first element to extend a connection from the calling line to the said second line dependent upon the call not being effaced.
48. In a telephone system, a calling line, a 20 non-step-by-step-directive single plane switch which will also function as a step-by-step directive switch in two planes, a line accessible from the switch, manually controlled means to initiate a call on the calling line to cause 25 the switch to automatically function in a single plane as a non-step-by-step-directive switch to connect the calling line to said accessible line, means for restoring the switch from the connected accessible line while 30 maintaining the initiation of the call, means whereby the switch will be disabled from thereafter automatically functioning as a non-step-by-step-directive switch and enabled to function as a step-by-step directive 35 switch in two planes consequent to its non-step-by-step directive functioning, and means whereby the switch will thereafter operate in two planes under step-by-step directive control for again connecting the calling line 40 to the said line before connected with dependent upon the call initiation being maintained.
49. In a telephone system, calling and 45 called lines, a switch, means controlled over the calling line for causing the switch to connect the calling line with the called line, a source of signaling current for application to the called line after the connection is effected, means controlled over the calling line 50 for causing a further operation of the switch before the said application and for disabling the said application, and means for delaying the said application to provide time for directly causing the last said means to be 55 operated.
50. In a telephone system, calling and 60 called lines, a switch, means controlled over the calling line for causing the switch to connect the calling line with the called line, a source of signaling current for application to the called line after the connection is effected, means controlled over the calling line 65 for causing a further operation of the switch before the said application to effect a second connecting operation of the switch and for 70 disabling the said application, and means for delaying the said application to provide time for directly causing the last said means to be operated.
51. In a telephone system, a called line, a 75 calling line, a linking switch, means controlled over the calling line for causing the switch to operate to pair the calling line with the called line, a relay in the switch operated to connect the paired calling and called lines in talking relation, means controlled over the called line responsive to a manual operation thereon for operating the relay, and means controlled over the calling line responsive to a manual operation thereon after pairing the lines to also control the operation of the relay to effect the talking relation between the calling and the called lines.
52. In a telephone system, a called line, a 80 calling line, a linking switch, means controlled over the calling line for causing the switch to operate to connect the calling line to the called line, a relay in the switch for rendering the connected calling line and the called line in talking relation, means for rendering the said relay operated responsive to a manual operation on the connected called line at will, and means alternatively controlled over the calling line at will to cause the operation of the relay to render the calling and called lines in talking relation.
53. In a telephone system, a called line, a 85 calling line, a linking switch, means for causing the switch to connect to the called line, a relay in the switch for connecting the calling line and the connected called line in talking relation, said relay effectively operated over the line called responsive to a manual operation, and means alternatively controlled over the calling line by manual operation thereon at will to also effectively operate the relay to connect the calling and called lines in talking relation.
54. In a telephone system, a called line, a 90 calling line, a linking switch, means for causing the switch to pair the lines, a relay in the switch for thereafter connecting the lines in talking relation, and alternative means whereby the relay can be effectively operated from either said line to connect the paired lines in talking relation.
55. In a telephone system, a called line, a 95 calling line, a linking switch mechanism, a signaling current source, means for operating the switch mechanism into connection with the called line, automatic means for thereafter applying the signaling current to the called line, a relay which may be effectively operated for disconnecting the signaling current from the called line without disconnecting the switch mechanism from the called line, means controlled over the connected called line responsive to a manual operation thereon for effectively operating the relay, and means alternatively controlled 100

- 115
- 120
- 125
- 130

over the calling line responsive to a manual operation for effectively operating the relay.

56. In a telephone system, a called line, a calling line, a linking switch mechanism, a signaling current source, means for operating the switch mechanism into connection with the called line, means for thereafter applying the signaling current to the called line, a relay effectively operated for disconnecting the signaling current from the called

10 line without disconnecting the switch mechanism from the called line, and means whereby the relay can be effectively operated from either said line.

57. In a signaling system, a switch mechanism for companioning two non-companioned lines, a relay energized for connecting the companioned lines into talking relation, and means alternatively operable from either said line after the lines are companioned for energizing the relay without disconnecting the switch mechanism from the called line.

58. In a signaling system, a switch mechanism for companioning two non-companioned lines, a relay energized for connecting the companioned lines, and means alternatively operable from either said line after the lines are companioned for energizing the relay without disconnecting the switch mechanism from the called line.

59. In a signaling system, a first line temporarily paired with a second line, a source of signaling current applied to the said second line, and means alternatively controlled from the first or the second line for disconnecting the signaling current without destroying the parity of the lines.

60. In a telephone system, a calling line having not to exceed two conductors, a called line, a switch, means for directly operating the switch over the calling line to extend a connection from the calling to the called line, a signaling current source, automatically applied means for applying signaling current to the called line from the switch, and means controlled over the calling line after completing the connection for preventing the said application while maintaining the switch in connection with the called line.

61. In a telephone system, a calling line having not to exceed two conductors, a called line, a switch, means for directly operating the switch over the calling line to extend a connection from the calling to the called line, a signaling current source, automatically applied means for applying the said signaling current source to the called line until disconnected by manual control from the called line, and means controlled over the calling line for preventing the application of signaling current while maintaining the connection with the called line.

62. In a telephone system, a calling line, a called line, a switch, means for directly operating the switch over a conductor of the

calling line to extend a connection from the calling to the called line, a signaling current source, automatically applied means for applying the said signaling current source to the called line until disconnected by manual control from the called line, and means controlled over said conductor of the calling line for at will disconnecting the signaling current while maintaining connection with the called line.

63. In a telephone system, a calling line, a called line, a switch, means for directly operating the switch over a conductor of the calling line to extend a connection from the calling to the called line, a signaling current source, and means under control of the said conductor of the calling line after the called line is connected with for applying the signaling current to the called line automatically until disconnected by manual control over the called line or not applying the signaling current without destroying the connection made to the called line.

64. In a telephone system, a trunk line, the trunk line leading to a first switch, a second switch, a calling line, means for operating the second switch to thereby effect a first connection from the calling line to the trunk line, means made operative consequent to the connection of the calling line to the trunk line for causing the said first switch to automatically connect to the said second switch, and means to thereafter automatically disconnect the said first connection whereby the calling line will be maintained connected with the trunk line but wherein the said first switch is now interposed in the connection between the said second switch and the trunk line.

65. In a telephone system, a trunk line, the trunk line leading to a first switch mechanism, a second switch mechanism, a calling line, means for operating the second switch mechanism to effect a first connection from the calling line to the trunk line, means made operative consequent to the connection of the calling line to the trunk line for causing the said first switch mechanism to automatically connect to the said second switch mechanism, and means controlled over the trunk line responsive to a manual operation after said first connection has been established for thereafter disconnecting the said first connection whereby the calling line will be maintained connected with the trunk line but wherein the said first switch is now interposed in the connection between the said second switch and the trunk line.

66. In a telephone system, a trunk line, the trunk line leading to a first switch, movable connecting terminals for the switch, a calling line, means for connecting the calling line to the trunk line, means controlled over the trunk line made operative consequent to the connection of the calling line to the trunk line for causing the said switch to automatically

- cally connect the trunk line to the calling line over a supplemental path and thereafter automatically disconnect the connection first existing with the trunk line whereby a connection between the calling line and trunk line is maintained but wherein the said switch and said movable terminals are now interposed between the calling line and the trunk line.
67. In a telephone system, a trunk line, a first switch mechanism terminating the near end of the trunk line, a second switch mechanism terminating the far end of the trunk line, a calling line, a called line, means controlled over the calling line for connecting the calling line with the trunk line, means for then operating the said second switch mechanism to extend a connection to the called line, and automatic means controlled over the trunk line responsive to a manual operation on the called line for establishing an alternative connection from the trunk line through the said first switch mechanism to the calling line without causing a lapse of connection between the calling line and the trunk line.
68. In a telephone system, a trunk line, a calling line, a first connecting means for connecting the calling line with the near end of the trunk line, a called line reached from the farend of the trunk line through switch mechanism directly controlled from the calling line, a second connecting means for connecting the near end of the trunk line with the calling line, and other means controlled over the trunk line from the called line responsive to a manual operation thereon for effectively operating the second means and for breaking down the connection established by the first means.
69. In a telephone system, a called trunk line, a calling subscriber line, a first connecting means operated over the calling line for connecting the calling line with the trunk line, a second connecting means for connecting the trunk line to the calling line, other means controlled over the trunk line responsive to a manual operation ensuing after said connection has been established for effectively operating the second means and for breaking down the connection established by the first means, and means controlled over the calling line for destroying the connection.
70. In a telephone system, a called two-conductor trunk line, a calling subscriber line, a first connecting means operated over the calling line for connecting the calling line with the trunk line, a second connecting means for connecting the trunk line to the calling line, other means controlled over a conductor of the trunk line for effectively operating the second means and for breaking down the connection established by the first means, and means controlled over the trunk line for destroying the connection.
71. In a telephone system, a called trunk line, a calling subscriber line, a first connecting means operated over the calling line for connecting the calling line with the trunk line, a second connecting means for connecting the trunk line to the calling line, other means controlled over a talking conductor of the trunk line for effectively operating the second means and for breaking down the connection established by the first means, and means controlled over the trunk line or alternatively over the calling line for destroying the connection.
72. In a telephone system, a trunk line, a calling line, a called line, a first connecting means for connecting the calling line with the trunk line, a second connecting means for connecting the trunk line with the calling line, a third connecting means for connecting the trunk line with the called line to complete a connection from the calling line to the called line, and other means controlled by closing a circuit path over a talking conductor of the called line for effectively operating the second means and for breaking down the connection established by the first means.
73. In a telephone system, a trunk line, a calling line, a called line, a first connecting means for connecting the calling line with the trunk line, a second connecting means for connecting the trunk line with the calling line, a third connecting means for connecting the trunk line with the called line directly controlled from the calling line in order to complete a connection from the calling line to the called line, and other means automatically controlled from the called line consequent to a manual response thereon to close a circuit path for effectively operating the second means and for breaking down the connection established by the first means.
74. In a telephone system, lines, a trunk line, a selective switch terminating said trunk line, means for seizing the trunk line, automatically applied means effective responsive to said seizure for causing the switch to first operate as a selective switch to test for and seize the first idle one of first said lines tested, automatic means for disconnecting the switch from the seized one of first said lines, automatically applied means effective responsive to said disconnecting for thereupon disabling the switch from again selectively operating, and means rendered effective responsive to first said selective operation and disconnection to thereupon render the switch selectively responsive to automatic directive control dependent upon the said seizure of the trunk being maintained.
75. In a two-dimension connective wiper switch, means for causing the switch to automatically initiate the operation of the wiper from normal position in a first one of said dimensions to hunt for and seize the first idle

- line therein responsive to automatic control, means for restoring the wiper to normal position from the line seized, and automatic directive means for re-operating the wiper from its restored position in second said dimension but dependent upon first said means being maintained effectively operated.
76. In a selective switch, means operative for causing the switch to automatically hunt from its idle resting position for and seize the first tested idle line, means for restoring said switch from the line seized, and means operative dependent upon said seizing and restoring operation of said switch to thereafter be operable only responsive to additional automatic directive control but dependent upon first said means being maintained effectively operated.
77. In a selective switch, means operative for causing the switch to automatically hunt from its idle resting position for and seize the first tested idle line, means for restoring said switch from the line seized, and means operative dependent upon said seizing and restoring operation of said switch to thereafter be operable only responsive to automatic step-by-step directive control but dependent upon first said means being maintained effectively operated.
78. In a two-dimension directive switch, means operative for causing the switch to automatically hunt in a first said dimension from normal position for seizing the first tested idle line, means for restoring said switch from the line seized, and means operative dependent upon said seizing and restoring operation of said switch to cause the switch to thereafter first be operable in the second said dimension only responsive to another automatic directive control but dependent upon first said means being maintained effectively operated.
79. In a two-dimension directive switch, means operative for causing the switch to automatically hunt in a first said dimension from normal position for seizing the first tested idle line, means for restoring said switch from the line seized, and means operative dependent upon said seizing and restoring operation of said switch to cause the switch to thereafter first be operable in the second said dimension only responsive to automatic step-by-step control but dependent upon first said means being maintained effectively operated.
80. In a two-dimension directive switch, means operative for causing the switch to automatically hunt in a first said dimension from normal position for seizing the first tested idle line, means for restoring said switch from the line seized, means operative dependent upon said seizing and restoring operation of said switch to cause said switch to thereafter first be automatically selectively operable step-by-step directly only in the sec-
- ond said dimension, and automatically applied means effective consequent to the termination of last said operation for thereupon adapting the switch to thereafter selectively operate only in first said dimension, the said operation of last two means being dependent upon first said means being maintained operated.
81. In a telephone system, a calling line, a trunk line, a switch on the trunk line having selective access to the calling line, means for connecting the calling line to the trunk line, means responsive to the establishment of said connection to cause said switch to preselect said calling line, and automatic means effective dependent upon a manual operation on the calling line thereafter for effecting a new connection between the calling line and the trunk line in which said switch is interposed and first said connection of the calling line to the trunk line is destroyed.
82. In a telephone system, a calling line, a trunk line, a wiper switch on the trunk line having selective access to the calling line, means for connecting the calling line to the trunk line, means responsive to the establishment of said connection to cause said switch to preselect said calling line, and automatic means effective dependent upon a manual operation on the calling line thereafter for effecting a new connection between the calling line and the trunk line in which said switch and wiper are interposed and first said connection of the calling line to the trunk line is destroyed.
83. In a telephone system, a calling line, a trunk line, a called line, a switch on the trunk line having selective access to the calling line, means for connecting the calling line to the trunk line, switch means for extending the said connection to the called line, and automatic means effective dependent upon a manual operation on the calling line and also on the called line thereafter for effecting a new talking connection between the calling line and the trunk line in which first said switch is interposed in the connection and first said connection of the calling line to the trunk line is destroyed while a talking connection between the calling and called lines is thereafter maintained.
84. In a telephone system, a calling line, a trunk line, a called line, a wiper switch on the trunk line having selective access to the calling line, means for connecting the calling line to the trunk line, switch means for extending the said connection to the called line, and automatic means effective dependent upon a manual operation on the calling line and also on the called line thereafter for effecting a new talking connection between the calling line and the trunk line in which first said switch and wipers are interposed in the connection and first said connection of the calling line to the trunk line is destroyed.

while a talking connection between the calling line and called lines is maintained.

85. In a telephone system, a trunk line and terminating automatic switch, means for seizing the said switch from the remote end of the trunk line, means in the said switch operative consequent to the said seizure to cause the said switch to hunt from its normal position as a selector to seize the first unguarded line tested, means on the line seized for introducing a second called line into the connection, means on said second line for disconnecting said switch from said first unguarded line seized, and automatically applied means effective responsive to said hunting and disconnection for capacitating said switch to be thereafter first operated step-by-step by automatic directive control.

86. In a telephone system, telephone lines, automatic switches controlled from a calling one of said lines for extending a connection to a called one of said lines, means for supplying battery to said calling line, relay controlled means operative upon the response of the subscriber on the called line for reversing the direction of said battery supply, means controlled from said called line for then extending said connection to another called one of said lines, retaining means for maintaining the direction of current flow reversed after the receiver is replaced at the first called station and before a response is obtained at the second called station, and means for restoring the direction of flow of said reversed flow of current after a predetermined time in the event that no response is obtained from said second called station.

87. In a telephone system, a called line, automatic switch mechanism for extending connection to the called line, a source of signalling current, means for applying signalling current from said source to the called line upon effecting connection to the called line, and a slow-acting means for causing the signalling current application to the called line to be delayed a time after the called line is connected to.

88. In a telephone system, a called line, automatic switch mechanism for extending connection to the called line, a source of signalling current, means for applying signalling current from said source to the called line upon effecting connection to the called line, a slow-acting means for causing the signalling current application to the called line to be delayed a time after the called line is connected to, and means directly operated over the called line before the time for applying the signalling current for preventing the signalling current from being applied to the called line, while maintaining the connection to the called line thereafter.

89. In a telephone system, a calling line, a called line, automatic switch mechanism for extending connection from the calling line

to the called line, means operated over the connected to called line for breaking down the connection from the calling line to the called line, a tone source, and means for applying the tone source to the calling line to indicate that first said means has been operated.

In witness whereof, I hereunto subscribe my name this 14th day of October A. D., 1921.

HERBERT M. FRIENDLY.
